INDEX TYPE MULTIPLE SPINDLE
PANTOGRAPH MACHINE

Allen D. Gunderson, Racine, Wis., assignor to George Gorton Machine Co., Racine, Wis., a corporation of Wisconsin

Filed Jan. 31, 1955, Ser. No. 484,992
13 Claims. (Cl. 90—13.1)

The invention provides and relates to a multiple spindle, tracer controlled pantograph machine of the index type for scaled reproduction of a master on a work piece by milling, grinding, and the like operations; and the nature and objects of the invention and the several features thereof will be readily recognized and understood by those skilled in the art in the light of the following explanation and detailed description of the accompanying drawings illustrating what I at present consider to be a preferred embodiment or mechanical expression of my invention, from among various other forms, embodiments, constructions and combinations of which the invention is capable within the broad spirit and scope thereof as defined by the claims which are hereto appended.

It is a primary and a general object of my present invention to embody and incorporate a plurality of cutter spindles of the powered pantograph operated, tracer controlled types with a powered indexing worktable, into an integrated organization to provide a multiple cutter spindle, indexing type of machine having a wide range and extreme flexibility of selection of operations, for performing identical profile milling, grinding and the like operations upon multiple work pieces simultaneously, or to perform identical or different successive operations on one or more work pieces to profile mill, grind, or otherwise form thereon accurately scaled reproductions of multiple patterns or masters respectively controlling and dictating the movements over the work pieces of the multiple cutter spindles of the machine.

A further object is to provide such an indexing type profile milling machine having multiple pantograph operated and tracer controlled cutter spindle units in which each unit has its own powered master for dictating the operations of the pantograph and in which each unit has its own powered cutter spindle drive which is independent of the powered cutter spindle drives of each of the other units.

Another object is to provide a machine having a plurality of such powered master, tracer controlled pantograph milling units in operative association and relationship with a powered rotary work indexing table which provides a plurality of work stations thereon for successively moving or indexing work pieces mounted at such work stations into operative positions relative to the cutter spindles of said pantograph units for the performance by said units of master dictated profile milling operations on such work pieces.

A further object is to provide such a machine in which each tracer controlled pantograph milling unit is provided with a powered master for dictating the operations of its pantograph, with the powered master of each unit operable independently of the powered master of each of the other units in order that masters may be used providing different master patterns for reproduction on work pieces indexed into operative position for profile milling thereon by such milling units.

A further object is to provide such a machine in which profile milling operations may be performed by each pantograph milling unit at a different ratio of scaled reproduction from the pattern or master for that unit, from the ratios of scaled reproduction performed by each of the other milling units from the powered masters for such units, respectively.

2

Another object is to provide such pantograph operated, master-controlled profile milling units with independent spindle feeds for feeding the cutter spindles of the units to and from operative milling positions.

5 A further object is to provide such a machine in which the pantograph milling units have independent powered spindle feeds for feeding the spindles into the work during operation on the work and/or for feeding the spindles to and from cutting relation with the work.

A further object is to associate and relate such powered cutter spindle down feed mechanisms with the powered masters controlling the pantograph operations of such milling units in an interlocked arrangement for coordinating and synchronizing the operations thereof and for 15 performing automatic milling cycles therewith.

Another object is to provide a powered indexing table in such a machine having a plurality of pantograph milling units in which the indexing table is interlocked with the several milling units in such a manner that the table 20 may be indexed only upon the completion of profile milling operations on a work piece at a work station with the pantograph milling units thereafter rendered inoperative for milling operations during the indexing cycle of the table.

Another object is to provide a system of interlocks by which the indexing table is rendered inoperative for indexing whenever a cutter spindle of one of the pantograph milling units is in milling relation with the work piece.

30 A further object is to provide an interlock system in such a profile milling machine by which a cutter spindle of any one of the pantograph milling units of the machine cannot be fed to operative milling relation with the work piece during indexing by the index table.

35 A further object is to provide a reversible, infinitely variable speed drive for the powered master of each of the pantograph milling units of such a profile milling machine so that the rate of movement of a cutter by a cutter spindle through a work piece may be controlled over an infinite range to meet the requirements of the work pieces and the profile milling operations being performed thereon, and further so that the direction of movement of a cutter through a work piece may be reversed, with all of such controls for each pantograph milling unit being independent of the controls for each 45 of the other units.

Another object is to provide an independent and infinitely variable speed control for the powered down feed mechanism of each of the pantograph milling units.

50 A further object is to provide a cutter spindle down feed mechanism for a pantograph milling unit in which a cutter head and cutter spindle unit is engaged by a forming guide with such forming guide being power fed by the mechanism to feed the cutter spindle.

55 A further object is to provide such a power fed forming guide with a mounting having cross-compound adjustment for facilitating accuracy of adjustment and wide range of set-up for the forming guide to meet the conditions of any particular milling operation.

60 Another object is to provide a power driven master unit for a pantograph operated and controlled cutter spindle which will have extreme accuracy in operation for precise movements of a cutter spindle in scaled reproduction of the pattern or master provided by such powered master unit.

65 Another object is to provide an adjustable mounting arrangement for such a powered master unit by which a wide range of adjustments may be obtained for practical, efficient operations of a master unit for a variety of work pieces and profile milling operations to be performed thereon.

A further object of the invention is to provide a de-

sign and arrangement of such a profile milling machine having a plurality of pantograph milling units of the power driven master types in which any desired number of such pantograph milling units may be utilized within the design limits of any particular machine of the invention; and further to arrange such a machine in such a manner that pantograph milling units may be removed therefrom or added thereto as may be desired or required for any particular milling operations.

And a further object is to provide an adjustable indexing table so arranged and integrated with a plurality of pantograph milling units as to permit of a wide variation of indexing positions for the work piece stations on the table relative to the milling cutters of the pantograph milling units to meet the requirements of different work pieces and profile milling operations by adjusting the worktable for different distances or degrees of indexing steps and the indexing sequences thereof.

With the foregoing and various other objects, features and results in view which will be readily apparent from the following detailed descriptions and explanations, my invention consists in certain novel features in design, constructions and combinations as will be fully referred to and specified hereinafter.

Referring to the accompanying drawings in which similar reference characters refer to corresponding parts and elements throughout the several figures thereof:

anism of FIG. 11, with the downfeed cam housing being shown in horizontal section.

FIG. 13 is a schematic wiring diagram of the several operating motors and power circuits for the machine of FIG. 1.

FIG. 14 is a schematic view of the control circuit network for the example machine of FIG. 1, powered from the power circuits of FIG. 13.

Basically, my invention is characterized by an indexable worktable, say a rotary table, on which there is provided a plurality of work stations spaced therearound with a plurality of pantographic type milling units spaced apart around the indexing table and each incorporating therein a rotary cutting spindle which is positioned by the unit over the indexing worktable so that the work stations on that table may be successively indexed to working positions below the several cutter spindles. The indexing table is suitably powered and the pantograph units also each include a powered spindle drive and a powered master from which the pantograph mechanism of the pantograph milling unit is controlled for effecting operations of the cutter spindle to precisely reproduce on a work piece the pattern or master defined by the powered master. In some instances each pantograph milling unit of the multiple units combined in operative association with the indexing table, is also provided with an independent, powered spindle feed by which the spindle may be fed to cutting position in the work piece at a work station positioned in operative relation with such cutter spindle. And, in accordance with my invention, the powered indexing table and the powered spindle drives, the powered masters and the powered downfeeds of the pantograph milling units are suitably electrically interlocked in a manner to prevent operational interference between the powered mechanisms and the functions which they are intended to perform cooperatively and in proper sequence relationship in the efficient operations of a machine or organization of the invention in which incorporated and integrated.

Thus, a machine of the invention having the foregoing basic characteristics can efficiently and at high rates of production perform various pattern or master-controlled profile milling operations, in either two-dimensions or three-dimensions, upon work pieces on the work stations indexed to operative positions at the several pantograph milling units. With such an organization, as provided by the invention, each pantograph unit may be controlled by and from a different pattern or master so that different profile milling operations may be performed on work pieces presented to the several pantograph units, respectively, with the result that work pieces of different finished forms may be simultaneously milled to their respective finished forms by the several pantograph units; or work pieces of the same finished form may be milled to such finished form by successive and different operations performed upon each work piece as it is successively indexed to working positions relative to the several pantograph units to which the work piece is indexed may perform the finishing operation by which the work piece is completed; or, depending upon the number of pantograph units which the organization includes, several work pieces may be simultaneously rough-milled by one group of the pantograph units and then indexed to another group of the pantograph units for simultaneous finishing milling operations thereon; or work pieces of the same finished form may be simultaneously milled at all or a plurality of work stations from identical powered masters on the several pantograph units. It is thus a basic characteristic and an important feature of a machine organization of my invention that great work flexibility is obtained and a wide range of milling operations may be performed therewith by various set-ups of the pantograph units through the use of different controlling patterns or masters, as well as by various indexing operations which may be carried out

by the indexing table to present various sequences, or groupings, or permutations of work stations selectively to the cutter spindles of the several pantograph units.

An exemplification of the principles, constructions, combinations and functions of the invention is presented and disclosed herein in an embodiment which provides an indexing type pantograph milling machine having four (4) cutter spindles each of which is included and incorporated in a pantograph unit for operation by the pantograph of that unit through a tracer dictated and controlled by and from a powered pattern or master unit for causing the milling tool or cutter on the cutter spindle of such unit to precisely reproduce on a work piece in accurately scaled relation, the master or pattern defined by the powered master for that unit. Expressions and embodiments of my invention are not, however, in any sense limited to the number of pantograph units and their included cutter spindles which a machine embodiment of the invention may include, as the invention contemplates and intends the provision of machines having two or more pantograph units and cutter spindles thereof, and the invention is not, therefore, limited to the four (4) spindle embodiment of this present example.

Further, in the selected example of the invention here presented, each of the spindle operating pantograph units provides a powered downfeed for a spring loaded, upwardly biased cutter spindle assembly, such feed mechanism being of the type that controls and dictates a progressive feed of the cutter spindle to the work by a master cam which has its independent power means. However, attention is here directed to the fact that the invention is not limited to this type of feed mechanism as it contemplates and includes not only different types of powered feeds for the cutter spindles, but the use of pantograph units having no spindle feeds in the sense of a distinct power feed for those instances where work is to be performed to a constant predetermined depth of cut, all as will be specifically referred to and discussed more in detail hereinafter in the descriptive portions of this specification dealing with the power feeds of the present example.

The pantograph units herein disclosed for the machine of this example are of the two-dimensional type but three-dimensional effects can be obtained through the use of so-called forming guides, as will be referred to hereinafter. However, the use in the example machine of pantograph milling units of the two-dimensional type is not in any sense intended to limit the invention to the use of two-dimensional units, as pantograph units for three-dimensional work are intended to be employed by and are included in the invention for work piece operations calling for three-dimensional reproduction from patterns or masters. The pantograph units herein disclosed in the example embodiment are of types for performing milling operations by the use of rotary milling cutters, mills and the like, but as will be obvious to those skilled in the art, pantograph units may be provided for grinding operations, or in fact for performing any material removing operations by which a work piece may be shaped or formed, or any portion thereof shaped or formed, in precise scaled reproduction of a master or pattern, and my invention intends use of and includes such material removing operations and any equivalents thereof. And it is here pointed out that for the purpose of brevity the expressions "cutter spindle" or "spindle," are used herein in a broad and generic sense to include the milling cutter, grinding tool or other material removing member to be mounted thereon.

General Organization

The general organization of the example machine, referring now to the accompanying drawings, includes the powered index table unit TU which includes and provides the horizontally disposed, rotary worktable T mounted in elevated position on a supporting frame struc-

ture which provides a base plate 10 with the vertically disposed structural frames 11 spaced therearound and extending upwardly therefrom and on which a table or platform 12 is mounted in horizontally disposed position on and across the upper ends thereof. This platform 12 is provided with a circular opening 14 therein which is surrounded by an annular member or mounting ring 15 positioned on the upper side of platform 12 and on which the index table unit TU is mounted and supported. The index table unit TU is a self-contained, powered unit for step-by-step work piece indexing rotation of the indexing table T thereof. The supporting frame structure is enclosed by a side wall 16 which is secured therearound in vertically disposed position between the base plate 10 and the elevated platform or table 12. It is to be noted that in this particular embodiment of the invention the table or platform 12 does not extend completely around the central opening 14 thereof but is of "horseshoe" or arcuate form in plan and terminates at its forward transverse edges 12a and 12b to merge into the front or forward side of the frame structure at spaced locations at opposite sides thereof so as to provide an operator station from which the forward portion of the periphery of the indexing table T is readily accessible for loading and unloading work pieces on those work stations of the worktable positioned at the forward side of the frame structure by indexing rotation of the worktable.

In this example four (4) pantograph milling units P1, P2, P3, and P4 are mounted on the elevated platform 12 in positions spaced equidistant apart angularly around the indexing table T with each of these pantograph units being located radially relative to the center or axis of rotation of the indexing worktable T. The pantograph milling units P1, P2, P3, and P4 include the vertically disposed cutter spindles S1, S2, S3, and S4, respectively, positioned thereby for independent universal lateral movements over the indexing worktable T and the path through which the work stations on the indexing table T are indexed or displaced by rotation of that table.

In the example machine having four (4) pantograph units, the rotary indexing table T of the powered index table unit TU is provided on the upper side thereof spaced therearound adjacent but spaced inwardly from the periphery of the table with a plurality of work stations W1, W2, W3, W4, W5, W6, W7, and W8. The rotary index table unit TU may be set-up for indexing through steps 45°, 90°, or 180°, or in fact any desired angular distance of indexing step, depending upon the requirements of the particular work pieces to be produced and of the milling operations to be performed thereon, all as will be explained hereinafter in detail. In the arrangement and set-up of the machine here disclosed the pantograph units P1, P2, P3, and P4 are all located spaced apart on and around the platform 12 of the supporting structure at the rear of a center line across the machine passing through the axis of rotation of the indexing table T from left to right when facing the machine, with the pantograph unit P1 positioned with its longitudinal center located 22½°, the pantograph unit P2 positioned with its longitudinal center located 67½°; the pantograph unit P3 positioned with its longitudinal center located 112½°; and the pantograph unit P4 positioned with its longitudinal center located 157½°, rearwardly around the half-circle from such center line. Thus, each of the pantograph units P1, P2, P3, and P4 is positioned with its longitudinal center located radially relative to the axis of rotation of the indexing worktable and spaced equal angular distances apart on the platform 12 around the rear side of the indexing worktable T. Thus, for indexing by the worktable T to locate the work stations W1, W2, W3, W4, W5, W6, W7, and W8 successively in operative positions at the cutter spindles S1, S2, S3, and S4, the work stations in this example machine are located at positions spaced 45° apart on and around the indexing worktable T of the index table unit TU.

In this instance the index table unit TU is operated and driven by an electric motor TM and, as will be hereinafter described and explained in connection with the operating control system for the example machine, may be either automatically operated through the milling cycle being performed by the pantograph units P1, P2, P3, and P4, or may be manually controlled by the operator from the operator station at the front side of the machine to index the table T and the work pieces thereon for each indexing step of the cycle.

The pantograph milling units P1, P2, P3, and P4 have their own powered cutter spindle drives which include the electric motors SM1, SM2, SM3, and SM4, respectively, mounted thereon as self-contained components thereof. The pantograph milling units P1, P2, P3, and P4 have their respective cutter spindles controlled in their movements over the work pieces being milled by separate and independent powered masters M1, M2, M3, and M4, respectively, which include the driving electric motors MM1, MM2, MM3, and MM4. The independent spindle drives for the pantograph milling units which are respectively operated by the motors SM1, SM2, SM3, and SM4 are under the control of the operator through master stop and start switches in the control circuits for the machine, such switches being located in an accessible position at the operator station at the front of the machine, as will be referred to hereinafter in describing and explaining the control circuit network for the example machine. Similarly, the driving motors MM1, MM2, MM3, and MM4 for the powered master units M1, M2, M3, and M4, respectively, are under the control of the operator through a control switch located at the operator station so that these powered masters may be simultaneously placed in operation with the start of operation of the cutter spindles S1, S2, S3, and S4 of the pantograph units.

In those machine organizations such as that of the example embodiment hereof, the pantograph milling units are provided with powered spindle feeds by which the cutter spindles of the pantograph units are fed to and from operative working positions, and these powered spindle feeds may include electric motors carried and mounted together with the feed mechanisms operated thereby, as self-contained components of the pantograph units. In this instance the power feeds for the cutter spindles S1, S2, S3, and S4 of the pantograph milling units P1, P2, P3, and P4 include the spindle feed driving motors FM1, FM2, FM3, and FM4, respectively. The motors FM1, FM2, FM3, and FM4 are connected into the control circuits for the machine in such a manner that upon starting the milling cycle by starting the cutter spindle drives and the powered master units for the pantograph milling units, the spindle down feed motors are simultaneously placed into operation, as will be referred to in the description of the control circuit network and the functioning of the machine which appears hereinafter.

While it forms no part of my present invention, a coolant system is provided for the example machine by which coolant is discharged in the usual manner on the work pieces and milling cutters engaged therein during the milling operations at the several work stations on the index table T. Such coolant system in this instance includes a coolant tank 17 mounted within the supporting frame structure, with a coolant pump and operating electric motor unit CM mounted in operative relation with said tank for forcing coolant therefrom under pressure to the discharge points at the cutter spindles through a coolant supply system (not shown). An annular vertical wall 18 having a greater internal diameter than the diameter of the indexing table T is mounted on platform 12 surrounding and concentric with the circular opening 14 in that platform and with the table T. Thus this circular vertical wall is spaced outwardly a distance from and around table T and forms with the portion of the platform 12 enclosed thereby an open top annular trough for drainage thereinto of coolant from the upper side of the table T

over and around the peripheral edge of that table. A return flow or drainpipe line 19 is provided for flow of coolant from the receiving trough provided by the circular wall 18 and platform 12 back to the tank 17. The coolant pump motor CM is in this example in a separate, independent circuit controlled by a switch to be referred to and identified hereinafter by which the operator may start and stop operation of the coolant system by the motor CM as he may desire and independently of the various other electrically operated components and mechanisms of the machine. Thus, with the machine of the example having the general organization and form of the components and mechanisms as hereinabove generally identified and described, the operator may stand at the operator station and through the actuating members for the electrical control switch components which are located in readily accessible position on a control box or panel CB, set the machine into the selected two-dimensional or three-dimensional milling operations at the work stations indexed to the pantograph milling units, while unloading work pieces from and loading work pieces to be milled on the work stations exposed to him at the operator station by the indexing worktable.

The Powered Index Table

The powered index table unit TU, per se, of the present machine example forms no part of my present invention and, therefore, may be of any desired design and construction capable of functioning to meet the requirements placed upon such a table unit by the integrated machine organization hereof. Suffice it for purposes of this disclosure to state that the unit TU includes a circular base 20 which is mounted on and around the ring member 15 which surrounds the circular opening 14 in the elevated platform 12 with the rotary table T being journaled on a suitable vertically disposed pivot stud 21 mounted on base 20. A suitable powered drive indicated generally by the reference character 22, is provided for rotating the indexing table T through its index steps, this drive including a pulley 23 on the outer end of a power input shaft 24. The indexing unit TU is powered by the motor TM which is adapted to be continuously operated. The motor TM is mounted in position suspended below the base 20 by a horizontally disposed motor mounting plate 25, the motor TM being mounted and supported on the plate in horizontally disposed position with its armature shaft 26 parallel with the input shaft 24. The motor driven or armature shaft 26 mounts on an outer end thereof the driving pulley 27 which is connected by a suitable driving belt 28 in driving connection with the pulley 23 on the input shaft 24. This rotary index table unit TU is of a design, construction and operation familiar in the art and is of that well-known type in which the underside of the table T mounts thereon so-called Geneva plates 29 which are operatively engaged by a so-called Geneva arm 29a which is mounted and journaled in position at the upper side of the base 20 for operative engagement with the Geneva plates. The Geneva arm 29a on the base 20 is rotated from the power drive 22 of the unit and successively engages the Geneva plates 29 on the table to thereby rotate the table in successive steps with intervals therebetween at which the table is at rest and in locked position, through angular distances as determined by the particular size and set-up of the Geneva plates and the Geneva arm which engages such plates and rotates or indexes the table through its successive index steps.

The motor TM by which the rotary index table unit TU is powered is suitably connected into the power and control circuits of the machine of this example for indexing operation under the control of the operator, as will be hereinafter fully described and explained. During operations of the machine the motor TM of the indexing unit TU is continuously operated, and suitable clutch mechanisms familiar to the art in this type of unit, are utilized to engage and disengage the Geneva arm with and from

the driving mechanism therefor which is powered by the motor TM.

As this type of indexing table unit TU is in commercial use and well known, it will only be necessary herein to specifically refer to and disclose those of the elements and components of the unit which are operatively related and controlled and synchronized with components and mechanisms of the machine of my present invention.

Referring now to FIG. 6, the unit TU includes a latch plate 29b which is rotatably mounted and which is associated with and controls the rotation of the Geneva arm 29a. This rotary latch plate is in turn controlled by a pivoted lock arm 29c which is adapted to be engaged with the latch plate. The lock arm 29c is in turn controlled by and from a latch lever 29d, which is under the control of the latch return spring 29e. The latch lever 29d is pivotally coupled by a link 29f with the outer end of the armature 29g of the actuating solenoid 207.

A limit switch 1LS, which may be of the microswitch type and which is normally open is incorporated in the table index unit TU and has an actuating member 29h. The rotary latch plate is provided with operating pins 29k thereon which are adapted to engage the switch actuating member 29h as they reach predetermined positions in the step-by-step rotation of the latch plate.

In the operation of the index table unit TU in the example machine, when it is desired to effect indexing of table T through an index step, the solenoid 207 is energized which, through link 29f, causes the latch lever 29d to release the lock arm 29c from contact with the latch plate 29b. The latch plate 29b rotates with the Geneva arm 29a which in turn results in indexing rotation of the table T to its next position of index where it is locked by the unit until it is again actuated through an indexing step. As the indexing table T goes into its locked position of index, an operating pin 29k will engage the switch actuating member 29h and cause an operation of the switch to momentary closed position. Upon release of operating engagement of member 29h by a pin 29k, the switch 1LS will automatically return to its normal open position.

The Powered Master-Driven, Tracer-Controlled Pantograph Milling Units

The pantograph milling units P1, P2, P3, and P4 are of identical design and construction and include the identical rotary cutter spindles S1, S2, S3, and S4, respectively, which are universally laterally movable by the pantograph milling units in two dimensions, while in units for three-dimensional work are adapted to be axially movable in the third dimension. As each pantograph milling unit is identical in construction and in functioning in the example machine, a detailed description of the construction and functioning of one of such units will suffice as a description for all of the units. Hence, referring to the pantograph milling unit P3 as shown in FIG. 2, a base 30 is provided by which the unit is securely mounted and attached in rigid position on and to the upper side of the elevated platform 12 of the supporting structure for the example machine. From the base 30 a vertically disposed column 31 extends upwardly and terminates at its upper end in a forwardly, inwardly extending neck 32. The unit P3 is mounted in position on the platform 12 so that the longitudinal center through the column 31 and its inwardly extending neck 32 lies on a radius line passing through the axis of rotation of the index table T, and each of the other units P1, P2, and P4 with their columns and inwardly extending necks 32 is also so mounted and positioned on platform 12 and relative to the index table T and its axis of rotation. The column 31 and its neck 32 are preferably cast or otherwise formed integral and on the upper side from end to end thereof there is provided the longitudinally disposed slideway 32'. The column 31 of the unit P3, and of each of the other units, has cast integrally therewith, or otherwise provided thereon, the horizontally disposed, vertically spaced ears

33 which are positioned adjacent the outer end of one side thereof and extend outwardly from and at an angular relation to the column. In this particular instance, these spaced ears 33 on the column 31 of each pantograph unit extend from the left-hand side of the column when facing a unit from the front or operator station of the machine. These spaced ears 33 form a bracket structure in and between which there is journaled for rotation about a vertical axis a pivot shaft 34 which is formed on or which carries the inner end of a motor mounting arm 35 which extends outwardly from one side of the ears 33 and which mounts and supports at the outer end thereof the spindle driving motor for the unit, being the motor SM3 in the case of the pantograph milling unit P3 now being described. The motor mounting arm 35 is provided with a laterally outwardly extending mounting plate 36 adjacent the outer end thereof which mounts thereon at the outer side of the arm 35 the motor SM3 in position with its armature or driving shaft vertically disposed and extending through the mounting plate with a pulley 37 mounted on the upper end of the shaft above plate 36. Thus the cutter spindle driving motor for each pantograph milling unit, such as the motor SM3 of the unit P3, is mounted and carried by the arm 35 and the pivot shaft 34 for horizontal swinging through an arcuate path in either direction about the axis of shaft 34 as a center. The functioning and the purpose of such horizontally swinging spindle drive motor mountings for the pantograph milling units will be described more in detail hereinafter.

On the same side of the column neck 32 at which the motor mounting ears 33 are provided but adjacent the inner end of the neck 32, there is provided an outwardly and inwardly extending horizontally disposed arm 38 which at its outer end provides in this example integrally therewith the horizontally disposed vertically spaced ears 39 for pivotally mounting therein the cutter head and cutter spindle carrying links which are actuated by the pantograph linkage of the pantograph milling unit, as will be described and explained in detail hereinafter.

A slider head 40 is mounted on and slidably received in the groove or slideway 32' on the upper side of the neck 32 of each column structure of a pantograph milling unit, such as the unit P1. This slider head is an elongated member having a length relative to the column 31 and its neck 32 such that in normal position the inner end thereof extends a slight distance radially inwardly over the adjacent peripheral portion of index table T and the outer end thereof extends over and above the upper end 50 of the column 31 and its neck 32. The outer length portion of the slider head 40 of each pantograph milling unit is provided with a longitudinal groove or slideway 41 thereacross with a slot 42 extending through the slideway for a substantial portion of the length thereof. The slider head 40 is provided with another groove or slideway 43 therein disposed longitudinally thereof and extending inwardly from the inner end of the slideway head to a location with its outer end spaced a distance inwardly from the inner end of the slideway 42, all as will be clear by reference to FIGS. 7 and 8 of the drawings. The inner end length slideway 43 of the slider head 40 is provided with a slot 44 through the head for a distance along the bottom of the slideway for a purpose to be hereinafter described.

Each slider head 40 of the pantograph units P1, P2, P3, and P4 has extending from one side thereof in laterally offset relation thereto, in this instance the right-hand side thereof when facing the pantograph units from the index table T, a column or post 45 which is cast integral with the slider head and which extends vertically upwardly spaced to one side of the slideway 43 adjacent the inner end of the slider head. A hanger arm 46 is formed integral with the upper end of the post 45 and extends inwardly therefrom in horizontally disposed position 75 over and across the adjacent inner end of the slider head

40 to a position with its inner end disposed over the table T spaced a distance inwardly from the inner end of the slider head 40. The inner end of the hanger arm 46 mounts or receives therein a pivot pin or stud 47 which is adapted to pivotally mount thereon the pantograph linkage 50 of the pantograph milling unit, as will be herein-after described.

The pantograph milling units P1, P2, P3, and P4 are provided with pantograph linkages 50 of the parallelogram type, each of which includes the parallel upper bars 51 pivotally coupled at their opposite ends to the adjacent ends of the parallel lower bars 53. Each pantograph linkage 50 is pivotally hung and supported in horizontally disposed position from the underside of the hanger arm 46 of the slider head 40 by the pivot pin or stud 47 which pivotally connects with the usual slider block 54 on the adjacent upper arm 52 of the pantograph linkage. Thus mounted, the pantograph linkage 50 is swingable in a horizontal plane about the pivot pin or stud 47. One of the lower bars 53 is extended outwardly across and above the slider head 40 to provide the outwardly extending tracer arm 55. The pantograph linkage for each of the pantograph milling units P1, P2, P3, and P4, which is controlled and operated about the pivot pin or stud 47 by the tracer arm 55, is adapted to be coupled to a cutterhead or cutter spindle barrel assembly 60 which mounts and journals therein the rotary cutter spindle for the pantograph milling unit.

Each of the rotary cutter spindles S1, S2, S3, and S4 is identical and each is mounted in its pantograph unit by an identical cutterhead 60 for operation in an identical manner under the control and dictation of the pantograph linkage 50 for the pantograph milling unit in which such cutter spindle is incorporated. In this example each cutter spindle is mounted and journaled in the cutterhead assembly or unit 60. Each cutterhead and cutter spindle unit 60 includes the barrel or casing 61 having at the upper side thereof and located axially thereon the vertically upwardly extending follower point or guide pin 62. The cutter spindle, say for example, the cutter spindle S1 of the pantograph unit P1 is journaled in the casing 61 to form therewith the unit cutterhead assembly 60 which is adapted to be mounted in the pantograph unit in position with the cutter spindle, say cutter spindle S1, in vertically disposed position and axially aligned with the follower or guide pin 62 at the upper side of the cutterhead unit 60. In certain instances the cutter spindle is mounted in the barrel or casing of a cutterhead and spindle unit for vertical axial movements therein, while in other instances such a cutterhead and spindle unit 60 is mounted for vertical displacement bodily as a unit on the structure on which mounted to thereby vertically axially displace and raise and lower the cutter spindle from and to its operative milling position. As the specific construction of the cutterhead and cutter spindle unit utilized forms no part of my present invention, except insofar as the unit is located and functions in integrated and combined relationship in a machine organization of the invention, it is not believed necessary to make any detailed disclosure thereof herein. Such cutterhead and spindle units are known to the art and are in use, being exemplified in such U.S. patents as Nos. 1,562,237, 1,956,505, 1,959,269, 2,000,838, 2,557,876, 2,645,161, and 2,658,423.

Each cutterhead and cutter spindle assembly forming unit 60 is adapted to be mounted for universal lateral movements in a horizontal plane under the control of the pantograph linkage 50 of a pantograph milling unit by a system of supporting links pivotally mounted for horizontal swinging on and from the arm 38 and ears 39 thereof which extend from one side of a slider head 40, as hereinbefore referred to and described. This cutterhead and cutter spindle unit mounting linkage, referring now to the pantograph milling units as illustrated in FIGS. 2, 3 and 7, includes the horizontal link 63 pivotally mounted at one end thereof on the ears 39 of arm 38 by a ver-

tically disposed pivot pin or stud 63' extending between and mounted at its opposite ends in the spaced ears 39, and a cutterhead mounting and carrying link 64 which is pivotally coupled by pivot pin 65 to the outer free end of the link 63. This cutterhead mounting link member 64 extends horizontally from the link 63 and is formed to provide the vertically spaced, generally parallel upper and lower arms 66 and 67 which are unconnected and spaced apart at their outer free ends to form an unobstructed space therebetween. The cutterhead and cutter spindle unit 60 for each pantograph milling unit in which the linkage 63 and 64 is included, is mounted in vertically disposed position on the upper side of the lower arm 67 of the link 64 in position between that arm and the upper arm 66. The overall height or vertical dimension of the cutterhead and spindle unit 60 between the lower end thereof on arm 67 and the upper end or follower point of the pin 62 is less than the distance of the spacing between the arms 66 and 67, so that there is unobstructed space between the upper end or follower point of the pin 62 and the upper arm 66 of the cutterhead unit mounting and carrying link 64. In this example in mounted position of a cutterhead and cutter spindle unit 60 on the lower arm 67 of the link 64, the cutter spindle is suitably spring-loaded and in effect "floating," being continuously biased in the upward direction toward its raised inactive position. Thus the cutter spindle is fed downwardly to operative milling position by forces applied thereto through the follower pin 62 to overcome the biasing forces applied by the spring loading for the cutter spindle.

Each of the cutter spindles S1, S2, S3, and S4 is mounted and journaled in and forms a component of a cutterhead assembly or unit 60, and in each instance with a unit 60 and its cutter spindle in mounted operative position on the lower arm 67 of a link 64, the cutter spindle itself extends downwardly through a distance below the arm 67 of the link 64 on which it is mounted. A driven pulley 68 is mounted on and fixed to each cutter spindle on the depending length thereof which extends below link arm 67 on which it is mounted. The driven pulley 68 on each cutter spindle is connected in driven relation by a belt B with the driving pulley 37 which is mounted on the power shaft of the cutter spindle drive motor swingably carried by the arm 35 of the pantograph unit of which such cutter spindle forms an operating component. A push-pull rod 69 is connected between the lower arm 67 of the link 64 in each pantograph milling unit and the motor mounting or support plate 36 on such arm 35 to cause the link 64 and the cutterhead unit 60 mounted thereon to swing together with arm 35 and the drive motor mounted thereon to thereby maintain the desired positioning and relation between the motor and its driving pulley 37 and the cutter spindle and its driven pulley 68 of the cutterhead 60 carried by the link 64. Each push-pull rod 69 is rotatably secured or coupled to the motor mounting plate 36 of the swingable arm 35 in position with its longitudinal axis passing through the vertical axis or center about which pulley 37 is rotated. Such rotatable coupling is made by providing the push-pull rod 69 with a ring or collar at its outer end which is connected to the motor mounted plate 36 concentric with the driving shaft of the motor and the pulley 37 mounted thereon for rotation thereon and relative thereto.

Each pantograph linkage 50 of each of the pantograph milling units P1, P2, P3, and P4, has a slider block 56 slidably mounted on that lower bar 53 thereof which is parallel with the opposite lower bar 53 which provides and from which the tracer arm 55 extends. The slider block 56 of each pantograph linkage 50 is pivotally coupled by means of a pivot pin or stud 57 with the upper arm 66 of the cutterhead carrying link 64 which is positioned directly therebelow. The slider block pivot pin 57 is positioned in axial alignment with the cutter spindle of the cutterhead unit 60 mounted therebelow. Thus, universal lateral movements in its horizontal plane of

each pantograph linkage 50 under the control of the tracer arm 55 will correspondingly universally laterally swing the link 64 and the cutter spindle of the cutterhead unit 60 carried thereby universally laterally over a work station of the rotary index table T which may be positioned therebelow. Each of the cutter spindles S1, S2, S3, and S4 is driven and rotated from its driving motor SM1, SM2, SM3, and SM4, respectively, as it is universally laterally swung by the operation of a pantograph linkage 50 through the driving belt B, the arm 35 with the spindle drive motor mounted thereon swinging horizontally about the pivot pin 34 with the distance between the axis of the motor and the cutter spindle which it drives being maintained constant through the medium of the push-pull rod 69 which transmits the movements of the link 64 as following movements of the cutter spindle driving motor.

The Powered Master Units

The universal lateral movements of the cutter spindle of each of the pantograph milling units P1, P2, P3, and P4 is effected through the actuation of the pantograph linkage 50 by the tracer arm 55 under the dictation and control of the powered master units M1, M2, M3, and M4, respectively, each of which is mounted on the outer length of the slider head 40 of the pantograph milling unit spaced outwardly a distance from the pantograph linkage 50 for that unit. It so happens that in this example the patterns or masters defined by the master units M1, M2, M3, and M4 are identical but it is to be understood that the pattern or master defined by each of the powered master units may be different from the pattern or master defined by the others, or by each of the others, and further, that such powered masters are interchangeable and removable for replacement by master units defining different patterns or masters to be reproduced on a work piece by the cutter spindle of the pantograph milling unit in which such master is included.

As each of the powered master units M1, M2, M3, and M4 of this example is identical as to construction, assembly, mounting, and functioning, it will only be necessary to specifically describe and explain one of the units, say the unit M1, for purposes of describing and explaining all of the units.

A powered master unit M1, M2, M3, or M4, is basically comprised of a master plate 70 which has formed therein a recess or pocket 71 open through the upper side of the plate, the side and end walls of which provide precisely finished and connected side surfaces 72 and end surfaces 73 which provide a continuous and uninterrupted endless master or pattern defining surface, a precise and scaled reproduction of which is to be milled or otherwise formed in a work piece. It will be noted that with the pattern or master plate 70 the opposite end wall surfaces 73 of the pattern defining pocket or recess are formed on a radius and join and uninterruptedly merge with the opposite side wall surfaces 72. While a particular form, shape, and contour of pattern or master defining recess 71 is shown for the master plate 70, it is to be understood, of course, that the variety of shapes, forms, and contours for such pattern or master defining recess is infinite, so the invention is in no sense limited or restricted to any particular pattern or master within, of course, the practical limitations of one of these powered masters and of the milling operations which they are to dictate and control.

As the powered master units M1, M2, M3, and M4 of this example are of the chain drive type, each master plate 70 having the pattern or master recess 71 formed therein is provided with a groove opening throughout its length through the top surface of the plate to provide a chain way or chain guide channel 74. In this example the chain way or guide channel 74 of each master plate 70 surrounds and conforms to the general contour of the

pattern or master defining recess 71, as will be clear by reference to FIG. 7 in connection with FIG. 8.

The master plate 70 of each of the master units is provided with the spaced parallel slots 75 therethrough which in this instance are disposed with their longitudinal axes transverse to the pattern or master recess 71 and the chain way 74, being located between that chain way and a side edge of the master plate. A sub-base or slider plate 76 having a slide rib 77 thereon is slidably mounted on the outer length portion of a slider head 40 with the slide rib 77 slidably received and engaged in the slide-way 41 of the slider head. Thus, the sub-base or slider plate 76 is slideable in either direction, that is, inwardly or outwardly on slider head 40 along a straight line path lying on a radius passing through the center of rotation or axis of the index table T. Suitable locking screws or bolts are provided for detachably securing the slider plate 76 in an adjusted position on the slider head 40, such screws or bolts being extended upwardly through the slot 42 which opens through the slider head in the bottom of the slideway 41.

A master plate 70 is mounted on the slider head mounted slider plate 76 in position with the slots 75 of the master plate disposed normal to and across the straightline path of adjustment of the slider plate on the slider head 40, with that half of the master plate 70 that has the master recess 71 and the chain way 74 therein extending inwardly from the slider head and slider plate toward the pantograph linkage mounting post 45. Thus mounted and positioned, it is to be noted that the master defining recess 71 and its surrounding chain way 74 are positioned disposed generally parallel with the slider head 40 and generally radially relative to the index table T. The slider plate 76 has attached thereto in position extending vertically upwardly therefrom the locking bolts or screws 78 which are headed at their upper ends, as by nuts threaded thereon and which extend through the slots 75 in a master plate 70 for engaging on the upper side of the master plate or suitable shoulders formed within and around the slots 75. Thus, by loosening the bolts 78 the master plate 70 may be adjusted transversely of the slider head 40 in either direction along a straightline path normal to the path of adjustment of the slider plate 76. This mounting and arrangement of a master plate 70 and slider plate 76 on a slider head 40 provides for cross-compound movements of the master plate in order to adjust that plate and its pattern or master-defining recess for work set-up purposes, as will be readily understood by those skilled in the art.

A master plate 70 thus mounted on the slider head 40 of a pantograph milling unit of the invention is in a position such that the tracer arm 55 of the pantograph linkage 50 for that unit extends outwardly over and above the portion of the master plate in which the pattern or master recess 71 and the chain way 74 are formed and provided. In accordance with the principles of my invention the tracer arm 55 of the pantograph linkage is operatively coupled with a chain drive mounted in the chain way 74 for causing a stylus or tracer mounted on the end of the tracer arm to follow the pattern or master-defining surfaces 72 and 73 of the master recess 71. In carrying out these principles in the present example, I provide an endless roller-type chain 80 which is placed in the endless chain way 74 in slideable engagement at one side thereof with the bottom wall 74' of the chain way for movement of the chain through and around the chain way. The chains 80 of the master units M1, M2, M3, and M4 are power driven by electric motors MM1, MM2, MM3, and MM4, respectively, mounted on and carried by the master plates 70 of the units. Each chain 80 is moved through and around its chain way 74 from its driving motor, by a sprocket wheel 81 which is mounted in the master plate 70 in position at the inner curved end 73 of the chain way in position at the inner side of the bight or bend of the chain located in and

passing around and through such curved end of the chain way. The chain driving sprocket 81 is horizontally disposed and is mounted on a driving shaft or spindle 82 which is journaled in vertically disposed position in the upper horizontal arm 83 of a motor supporting and mounting bracket structure, identified generally by the reference character 84, which is mounted and attached at the underside of a master plate 70 in position depending downwardly therefrom. The shaft 82 is journaled in a bearing assembly 85 and extends therefrom downwardly through the bracket structure 84. The shaft 82 at its lower end is journaled in an anti-friction bearing assembly 86 mounted on the bracket structure 84. A spur gear 87 is mounted on the shaft 82 for rotation therewith at a location spaced below the bracket arm 83 and the sprocket 81 thereabove. A reversible, infinitely variable speed drive unit 88 is mounted on the bracket structure 84 in position at the outer side of the shaft 82 and having a vertically disposed power output shaft 88a extending upwardly therefrom. A spur gear 89 of 20 smaller diameter than the gear 87 is mounted on the upper end of shaft 88a in position on such shaft in the plane of and in driving mesh with the gear 87. The motor MM1, MM2, MM3, or MM4 of the powered master unit M1, M2, M3, or M4, is mounted and secured at the lower end of the bracket structure 84 mounted on the master plate 70 of the unit in position with its armature shaft 88b vertically disposed and extending upwardly therefrom in vertical axial alignment with the input shaft 88c of the infinitely variable speed drive unit 88. The input shaft 88c extends downwardly from the unit 88 and is suitably operatively coupled in driven relation with the armature shaft 88b of the master unit motor, say, for example, the motor MM1 of master unit M1, as shown in FIG. 8.

The infinitely variable speed drive unit 88 is provided with a manual control lever 88S which extends radially outwardly from the upper end thereof by which the operator may selectively set the unit for delivery of the required rate of speed of rotation of the off-take or output shaft 88a and thus determine the rate of rotation of the sprocket 81 and the rate of speed of movement of the chain 80 through and around its chain way. The motor armature shaft 88b and the variable speed unit input shaft 88c are coupled by a suitable reversible coupling unit 88d which provides a radially outwardly extending manual control lever 88R by which the direction of rotation of the variable speed unit input shaft 88c may be reversed to thereby reverse the direction of movement of the chain 80 through and around the chain way 74.

The power driven roller chain 80 of each of the powered master units M1, M2, M3, and M4 is adapted to move a tracer or stylus 90 which is coupled with and is adapted to actuate the tracer arm 55 of the pantograph linkage of the pantograph milling unit. The tracer or stylus 90 in this example is comprised by a stud or pin 91 on which there is journaled and rotatably mounted a tracer roller 92 which is positioned in the pattern or master defining recess 71 for rolling engagement on and around the pattern or master-defining surfaces 72 and 73 of the recess 71. The tracer roller 92 has a diameter less than the minimum width at any point of the master-defining recess 71 of its master plate 70 so that this tracer roller may be held in rolling contact against and moved around to follow the endless pattern surface provided by and around the outer sides of that recess. A tracer or stylus carriage 93 is provided for connection with the power driven chain 80 and for coupling with the tracer or stylus 90 for moving the latter in following or tracing engagement with and around the master defining surfaces or the recess 71 in a master plate 70. The carriage 93 mounts therein the spaced pins or studs 94 which depend therebelow and which mount the rollers 95 journaled on their lower ends below the carriage. The carriage 93 is mounted in operative position 971 a master plate 70 with 75

the spaced rollers 95 thereof positioned in the chain way 74 above the chain 80 in that chain way. In this specific example the chain way 74 has the upper portion thereof above the chain 80 formed of increased width to provide the spaced shoulders 74" above and at and around opposite sides and ends of the endless chain 80, from which the opposite vertical surfaces extend upwardly to form tracks against which the rollers 95 may have rolling contact as the carriage is moved around the chain way by powered drive of the chain 80. One of the roller mounting pins 94 of the carriage 93 is extended downwardly a distance below the other of the pins 94 to provide a driving link pin 96 which is pivotally coupled and connected to a link of the driving chain 80 in a manner which will be clear by reference to FIG. 9. Thus, movement of the chain 80 around the chain way 74 will correspondingly move and carry with it the tracer carriage 93 which is pivotally connected thereto at the one point only provided by the driving link pin 96.

A slider bar or coupling member 100 is slidably yieldingly mounted in and extending transversely through the carriage 93 with its inner end positioned over and above the pattern or master-defining recess 71. The slider bar or coupling member 100 extends outwardly a distance 25 across a master plate 70 to terminate with its outer end located spaced a distance inwardly from the adjacent outer edge of the master plate. This coupling member 100 in this example takes the form of an open rectangular frame closed at its opposite ends and mounting therewithin a biasing spring 101 which may be of a coil type engaged at its outer end over an adjusting screw 102 threaded through such outer end of the member. The inner end of this biasing spring 101 is engaged at its inner end against the outer side of a pin or lug 103 mounted in fixed position in the carriage 93 and extending upwardly therefrom into the hollow frame which forms the coupling member 100, as will be clear from FIG. 5. Spring 101 is positioned between screw 102 and the pin or lug 103 on the carriage 93 under compression so that it acts to continuously bias the slidably mounted coupling member 100 outwardly through the carriage. The inner end of the slider bar or coupling member 100 is provided with a vertical bore therethrough in which there is mounted an annular microbearing 104 which provides axially therethrough a bore 105 for pivotally receiving and journaling therein a follower pin mounted in the end of a tracer arm 55.

The tracer arm 55 of a pantograph linkage 50 extends outwardly over the chain way 74 of a powered master unit, and in accordance with my invention I pivotally couple the outer end of a tracer arm 55 to the slider or coupling member 100 of the chain driven carriage 93, of a powered master unit, so that movements of the carriage and the coupling member thereon are transmitted to and translated as horizontal swinging movements of the tracer arm. In this specific example I provide a follower pin 106 in vertically disposed position extending transversely through the outer free end of a tracer arm 55 with the follower pin extending into the bore 105 of the microbearing 104 in the inner end of the slider or coupling member 100, so that the follower pin is rotatably mounted and journaled in and operatively connected to the coupling member 100. The lower end of the follower pin 106 may, as in the example hereof, be formed with an axial bore extending upwardly thereinto which fits down over and receives therein the pin or stud 91 of the tracer or stylus 90 with the follower pin 106 and the stud 91 being in axial alignment, to thus connect the follower pin and tracer or stylus for lateral movements together as a single unit. As the chain way 74 may not run truly parallel with and around the pattern or master surfaces 72 and 73 of the master recess 71, it follows that the distance between the axis of the follower pin 106 and of the link pin 96 on the carriage 93 may not remain constant as the carriage and the tracer or stylus are moved through

their cycle around the endless paths provided by the chain way 74 and the master recess 71. However, with the coupling member 100 being slidably mounted in the carriage 93 and being spring loaded by the spring 101, the coupling member is continuously biased outwardly relative to the carriage 93 to thereby yieldingly maintain the roller 92 of the tracer or stylus 90 in constant rolling contact with and against the pattern or master defining surfaces 72 and 73 of the master recess 71 in a master plate 70.

With the powered master of one of the pantograph milling units thus operatively coupled with the follower pin 106 on the tracer arm 55 of a pantograph linkage, when the drive chain 80 of the master unit is set into operation by its driving motor, such drive chain as it is moved around the continuous chain way 74 thus moves the carriage 93 and forces the tracer or stylus 90 and the follower 106 connected in axial alignment therewith to follow around the pattern defining surfaces 72 and 73 of the master recess 71. The movements of the tracer style and follower pin connected therewith are transmitted to the tracer arm 55 which is thus swung horizontally to thereby universally laterally swing the pantograph linkage and through the coupling of the latter with the cutter spindle carrying link 64 cause the cutter spindle of a cutterhead unit 60 mounted on such link to be moved universally laterally over a work station in precise and accurate scaled reproduction of the pattern or master defining surfaces 72 and 73 in the master recess 71.

As will be readily recognized by those skilled in this art the pantograph linkage 50 of each of the pantograph milling units P1, P2, P3, and P4 may have the ratio of reproduction thereof adjusted over the range of adjustments of which that particular linkage is capable. In the example hereof each of the pantograph linkages 50 happens to be set for a ratio of reduction of 8:1, that is, the milled reproduction performed on a work piece is precisely and accurately $\frac{1}{8}$ the size defined by the master surfaces 72 and 73 of the master recess 71 in a master plate 70. But, due to the great flexibility and wide range of operations made possible by the combination, relationships and integrated organization of a machine of the invention, it is possible in order to meet the work requirements of a particular work piece to have each of the pantograph linkages of each of the pantograph milling units set at a different ratio of reproduction. For example, one of the pantograph milling units could be set for a reproduction at a ratio of 3:1, a second at a ratio of 4:1, a third at a ratio of 5:1, and a fourth, say, at a ratio of 16:1, and this characteristic and feature of a machine of the invention is not changed by the fact of the number of pantograph milling units provided by the machine, that is, by a number less than or more than the four (4) pantograph milling units P1, P2, P3, and P4 of the example machine.

It has been determined with the chain type master unit of the example machine of the invention that abrupt turns in the driving chain track which generally follows and conforms to the shape of the pattern or master-defining surfaces will tend to cause rapid acceleration of the feed of a cutter through a work piece with resulting frequent cutter breakage. In order to overcome such tendency toward too rapid acceleration of a cutter through a work piece my invention provides a chain brake or snubber arrangement on the master plate 70 of each powered master unit. In the form of such a snubber herein disclosed, a master plate 70 is recessed and there is mounted in such recess for slidable movements along a straight-line path radially toward and from the driving chain 80, a snubber plate 110 which is positioned in the horizontal plane of the rollers 95 of the carriage and which projects a slight distance into the path of such rollers. This snubber plate 110 is spring biased continuously toward the path of the rollers 95 by a pair of biasing springs 111 and a suitable closure and guide plate 112 is secured over

the outer portion of the master plate recess and the snubber plate 110 slidably mounted therein. Plate 112 has an elongated slot 114 therethrough in which there is slidably received a limit pin 115 for determining and limiting the distance of projection of the snubber plate into the path of the carriage rollers. In this particular example, this snubber plate 110 is positioned to engage with a reentrant portion of the chain way immediately following the inner, relatively abruptly curved end of the chain way and the inner edge of the snubber plate 110 is formed convex to generally conform and correspond to the radius of curvature about which such reentrant portion is generated. The snubber plate 110 thus puts pressure against the carriage rollers 95 as they are forced therewith, so that regardless of the amount of slack which the chain 80 may have, it cannot overrun but must be pulled through the section of the chain way into which the snubber plate 110 yieldingly projects.

Each of the pantograph milling units P1, P2, P3, and P4 with its powered master units M1, M2, M3, and M4, is interlocked into the combined mechanisms making up the integrated organization constituting the example machine of the invention as herein disclosed. In carrying out such interlocking and integration, each pantograph milling unit upon the completion of its milling cycle as controlled and dictated by the powered master unit for such pantograph unit, is automatically brought to a stop through an electrical interlock system which opens the circuit to the drive motor for that spindle unit. In carrying out this feature of the invention, limit switches 2LS, 3LS, 4LS, and 5LS are mounted on and incorporated in the pantograph milling units P1, P2, P3, and P4 for automatically opening the circuits to the drive motors MM1, MM2, MM3, and MM4 of the master units for such pantograph milling units. As the master motor controlling limit switches for all of the pantograph milling units and their operating and interlocking arrangements and circuits are identical, only the limit switch 2LS for the master unit motor MM1 of the pantograph milling unit P1 will be described in detail, as such description will suffice to explain the arrangement and functioning of each of the others.

Referring now to the pantograph milling unit P1, a limit switch 2LS is mounted in fixed position on the outer side of the post 45 from which the hanger arm 46 for mounting the pantograph linkage 50 extends, with this limit switch thus positioned between post 45 and the adjacent inner end edge of the master plate 70 of master unit M1. The limit switch 2LS may be the microswitch type as shown in this example, and includes a switch actuating pin or plunger 118 which is horizontally disposed to extend outwardly therefrom in line with and for engagement by the adjacent side of the tracer arm 55 when that arm reaches a predetermined position at the adjacent end of the pattern or master recess 71 in the master plate 70 of the powered master unit M1. The limit switch 2LS is of the normally closed type, as are the identical limit switches 3LS, 4LS, and 5LS of the pantograph milling units P1, P2, and P3, respectively, to normally close a circuit therethrough in which connected, but which, upon depression of the switch plunger 118 by engagement with the tracer arm 55, will open this limit switch and thus open and break the circuit in which it is connected. As will be hereinafter fully described and explained, in the simultaneous milling cycle operations of the pantograph milling units P1, P2, P3, and P4, as such units complete their milling cycles and the tracer arms 55 reach the ends of the pattern or master recesses 71 at locations with the tracers 90 in such recesses at positions therein which define the ends of the milling cycles, the limit switches 2LS, 3LS, 4LS, and 5LS will be engaged by the tracer arms 55 of the respective milling units and will depress the switch plungers 118 and thus open all of these limit switches. The limit switches 2LS, 3LS, 4LS, and 5LS are connected in the circuits to the powered master unit driv-

ing motors MM1, MM2, MM3, and MM4, respectively, and when such limit switches are opened by the tracer arms 55 at the ends of the milling cycles, the motors are stopped and further operation of the powered masters is likewise stopped.

The Cutter Spindle Down Feed Mechanisms

A machine organization embodying the rotary index table T and the pantograph milling units P1, P2, P3, and P4 each with its self-contained powered spindle drive and powered master unit, as hereinbefore described and explained, presents an operative organization for 2-dimensional profile milling where the milling operations may be performed at a constant depth of cut throughout the milling cycle. In such operations each of the cutter spindles S1, S2, S3, and S4 may be set and fixed for a constant depth of milling cut when provided with a definite type and length of milling cutter and such setting can be obtained by means of what the art terms a forming guide positioned above and engaged by the follower pin or point 62 of a cutterhead and spindle unit 60, or a cutter spindle in such a unit, if spring biased, may be set and fixed for a constant depth of milling cut as the milling cutter is universally laterally moved over a work piece by the pantograph linkage under the dictation and control of the powered master for each pantograph milling unit.

However, in the example machine each of the pantograph milling units P1, P2, P3, and P4 includes as a self-contained component mechanism thereof a powered down feed by which a cutter on the cutter spindle of each unit may be progressively fed into the work piece as the milling cutter performs the milling cut therethrough while being universally laterally moved thereover under the dictation and control of a powered master unit. Each of such powered down feed mechanisms, as incorporated in the example machine, provides a power driven master down feed cam which progressively feeds a cutter spindle downwardly to predetermined depths through each cycle of one rotation of the down feed cam as synchronized with the movements of the tracer or stylus of a powered master unit.

Such a powered down feed mechanism may include a base plate or supporting frame structure 120 which is detachably secured on the inner length of a slider head 40 of a pantograph milling unit and which may provide at the underside thereof a slide for slidably fitting into the slideway 43 of such slider head, such adjustable mounting and attachment of the base frame structure 120 being carried out by a bolt 121 which extends down through the base 120 and through the slot 44 in a slider head 40 with the lower or under end of bolt 121 having threaded thereon a fastening nut 122. This supporting base frame structure 120, when in mounted attached position, has its outer end adjacent the inner side of a powered master unit mounted on the slider head 40 and has its inner end positioned adjacent the inner end of the slider head but spaced below a pantograph linkage 50 of a pantograph milling unit in which such downfeed is incorporated.

The motor for driving such downfeed mechanism is mounted with its armature or driving shaft in horizontally disposed position with its axis generally transverse relative to the slider head and the mounting base 120. The driving motor so positioned is located in laterally offset position relative to the slider head 40 and the supporting base 120 mounted thereon by means of the laterally extending bracket structure 124 on and to which the motor is attached. In this example the downfeed driving motor is positioned laterally offset from the base 120 at the left-hand side thereof and of each pantograph milling unit P1, P2, P3, and P4 when facing such units from the front of the machine. The downfeed mechanisms for the pantograph milling units P1, P2, P3, and P4 are identical and include the driving motors FM1, FM2, FM3, and FM4, respectively, mounted on the sup-

porting base frame structure 120 of each downfeed mechanism as described hereinabove.

A stud shaft 125 is mounted in vertically disposed position fixed to and extending upwardly from the supporting base frame structure 120 adjacent the inner end thereof. This stud shaft 125 is, in this instance, positioned with its vertical axis passing through the longitudinal center of the supporting base frame structure 120 and a slider head 40 on which the latter structure is mounted and attached. A cam spindle 126 is journaled on the stud shaft 125 by vertically spaced, annular anti-friction bearing assemblies 126a. This cam spindle 126 is formed to provide at the upper side thereof a radially outwardly extending horizontal flange 127 therearound to and around which flange there is attached and secured a worm wheel 128. A bell cam forming ring or annulus 129 is attached on the cam spindle 126 at and around the underside of the flange 127. This cam ring 129 is formed of progressively varying vertical depths therearound to provide the annular cam surface 130 which is thus spaced progressively varying vertical distances around the cam ring from the horizontal plane of the upper surface of the supporting base frame structure 120 on which the stud shaft 125 is mounted.

A drive is provided from the motor, say for example, the motor FM4, to the worm wheel 128 for rotating the cam spindle 126 and the bell forming cam 129 mounted thereon. This drive motor may, as in this example, include an infinitely variable speed gear set or transmission 131 in operative driven connection with the motor FM4 and having a power or drive take-off shaft 132 extending inwardly therefrom substantially parallel with the longitudinal center of the supporting base frame structure 120. The inner end of this shaft 132 is connected into a coupling unit 133 which, in turn, is coupled with and transmits driving power to a driving shaft 134 in general axial alignment with the shaft 132. Shaft 134 extends inwardly from the coupling 133 from a housing or casing structure 135 which has therein the spaced bearing assemblies 134a in which the shaft 134 is journaled. A worm 136 is mounted on the shaft 134 intermediate the shaft bearings 134a in engagement and driving mesh with the worm wheel 128 on the cam spindle 126. Thus the cam spindle 126 is power rotated from the motor to power rotate the cam 129 from the worm 136 and the worm wheel 128 which is in driven engagement with the worm.

Preferably the gear set or transmission 131 from the motor, say, the motor FM4, to the shaft 132 is of the variable speed type so that the rate of rotation of the bell cam 129 may be selectively determined to meet the cutter spindle downfeed requirements established by the conditions for any particular work piece milling operation. And, in any instance where it may be found desirable or expedient the driving motor may be of the reversible type or, other reversing means may be provided of any of the well-known types in the drive from the motor to thereby reverse the direction of rotation of the master feed cam 129.

The inner end of the supporting base frame structure 120 of each powered downfeed mechanism is provided with a vertically disposed frame 141 which depends therefrom and which provides at the inner side thereof the laterally spaced inwardly extending opposite side rails 142. At the lower end of the frame structure 141 and the vertical side rails 142 there is provided an end plate 143. A forming guide carriage 144 is vertically slidably mounted on and between the side rails 142 of the depending frame structure 141 for vertical straightline movements upwardly and downwardly on the frame structure. This carriage 144 is continuously biased upwardly by springs 145 which may be of the coil type and which are interposed between the bottom or end plate 143 and the carriage 144, the lower ends of the springs 145 being engaged over positioning pins 145a on the bottom plate 144 and the upper end lengths of the springs being extended

and received in vertical bores 145b formed in the carriage structure.

A forming guide bracket structure 150 which includes a base 151 and a forming guide mounting arm 152, is mounted and attached on the outer side of the carriage 144 by the base 151 which is secured in vertically disposed position on and against the outer side of the carriage with the forming guide mounting arm 152 of the bracket structure 151 extending in horizontally disposed position inwardly over and above a cutterhead and cutter spindle assembly unit 60 of the pantograph milling unit in which the downfeed mechanism is incorporated and embodied. As it is necessary for set-up and adjustment purposes that the forming guide mounting bracket structure 150 be capable of adjustment both vertically and laterally or horizontally on and relative to the carriage 144, my invention provides for cross-compound adjustment of the bracket structure. In this instance such adjustment is provided for by vertically elongated slots 146 which are spaced apart vertically and which extend through the body of the carriage 144. An adjustment plate 153 is positioned against the outer side of the carriage 144 and between that carriage and the mounting base 151 of the bracket structure 140 which is positioned in mounted position on and against the outer side of this mounting plate. The mounting plate 153 is provided with bores therethrough aligned with the carriage slots 146, and the mounting base 151 of the bracket structure 150 is provided with vertically spaced transversely elongated slots 154 therethrough which are aligned with and opposite the bores through the plate 153 and the vertically elongated slots 146 in the carriage. Headed attaching bolts 155 are extended through each of the mounting base slots 154 and extend inwardly through the bores in the plate 153 and the vertical slots 146 in the carriage 144, such bolts 155 at their inner ends being threaded into clamping nuts 156. Thus, by loosening the attaching bolts 155 the assembly of bracket structure 150 and plate 153 can be adjusted vertically upwardly or downwardly and the bracket structure 150 can be adjusted horizontally and laterally on and independently of the plate 153 for a final adjusted position of the forming guide mounting arm 152. In this specific example the plate 153 is provided with a transverse groove 157 thereacross and the inner side of the mounting base 151 of the bracket structure 150 is provided with an inwardly extending transversely transposed rib 158 thereacross which is slidably received in the groove 157 in the plate 153. Thus the bracket structure 150 is constrained to straightline horizontal adjustments in either direction by the rib 158 of mounting base 151 which is slidably received in the groove 157 in the plate 153. The horizontal lateral adjustments of the bracket structure 150 on the plate 153 of carriage 144 are effected by means of an adjusting screw 159 which is rotatably journaled on and extending through a side of the carriage 144 with its inner end length threaded into a horizontally disposed transverse tapped bore 159a in the mounting base 151 of the bracket structure 150.

The spring loaded carriage 144 thus mounts and carries the forming guide mounting bracket structure 150 for vertical movements upwardly and downwardly as a unit assembly. Such upward and downward movements of the carriage 144 and the bracket structure 150 are dictated and controlled by the combined actions of the biasing springs 145 and the master down feed cam 129 in accordance with the annular cam surface 130 provided by and around that cam. To this end a cam point or follower pin 160 is mounted in fixed position centrally on and extending vertically upwardly from the upper end of the carriage 144, with this cam point being yieldingly biased into sliding cam surface following engagement with the cam surface 130 of the downfeed cam 129 by the biasing action of the springs 145. It is thus apparent that as the downfeed cam 129 is power rotated from and by its driving motor, as the "high" portions of the cam engage

with the cam point 160 such point with its carriage 144 and the forming guide mounting bracket 150 will be forced downwardly. And, as "low" portions of the cam surface 130 reach the cam point 160, that point, with its carriage 144 and the forming guide mounting bracket 150 will, under the action of the biasing springs 145, be forced upwardly with the cam point 160 maintained in close cam following engagement with the surface 130.

A forming guide G in the form of a block 161 is removably secured and attached in horizontally disposed position at the underside of the arm 152 of the bracket structure 150 and this forming guide block 161 provides the forming guide surface 162 at the underside thereof. In the mounted assembled position of a downfeed mechanism 15 on a slider head 40 of a pantograph milling unit, the arm 152 of the forming guide mounting bracket 150 extends horizontally inwardly from the carriage 144 in position extending over and above the cutterhead and cutter spindle unit 60 with the forming guide follower pin 62 of that unit in slidable engagement with the undersurface 162 of the forming guide G. The area of surface 162 of forming guide G is, of course, sufficient to cover the area through which the pin 62 is universally laterally moved with the cutterhead and spindle unit 60 as that unit is universally laterally moved by a pantograph linkage 50 in the milling reproduction on a work piece of the pattern or master defined by the powered master unit for such pantograph milling unit. As each of the cutterhead and spindle units 60 of each of the pantograph milling units P1, P2, P3, and P4 of the example machine, is continuously spring biased upwardly, it follows that the downfeeding movements of such cutterhead and cutter spindle unit is effected by the "high" portions of the downfeed cam 129 by downward displacement of the carriage 144 and the forming guide G carried therefrom in engagement with the pin 62 as the cutterhead and spindle unit 60 is universally laterally moved over the work piece, while upward movements of the forming guide as the cam point 160 follows the rises to the "low" portions of the cam surface 130 will be followed by a cutterhead and spindle unit 60 with the pin 62 of that unit maintained in engagement with the forming guide G under the action of the spring loading and upward biasing thereby of the unit 60. In the present example machine each of the downfeed cams 129 has the cam surface 130 thereof generated so as to provide for progressive downfeed of a cutter spindle into the work piece as the cutter spindle moves the cutting tool in milling engagement through the work piece with such progressive downfeed being completed upon each milling cycle or pass of a milling cutter through the work piece. In other words, the cam 129 has its cam surface 130 so generated and formed that the maximum "low" point or portion of cam surface 130 is in engagement with the cam point 160 at the start of a one revolution milling cycle with the cutter spindle thus raised to its highest point for the cycle, so that as the cam 129 rotates, the cam surface 130 thereof will progressively downwardly feed the cutter spindle until the maximum "high" point or portion of surface 130 is reached at the end of one complete revolution. Upon the completion of such a revolution the cam surface 130 provides an abrupt transition from its maximum "high" to its maximum "low" point for the start of the next milling cycle. Obviously, feed cams presenting cam surfaces of other forms than the progressive feeding cam of this example may be employed as required to mill any particular work piece. Such cams may provide "dwell" for periods of milling at constant depths or may provide "high" and "low" portions in any desired sequence or arrangement, or may start a cycle at maximum depth and progressively feed upwardly through decreasing depths, as my invention is not limited to any particular form of cam or milled work piece produced therewith.

The example machine which is set up and which is mastered for a particular milling operation in a work piece in which the work piece is finish-milled to substantially

constant depth has each of the downfeed mechanisms of the pantograph milling units provided with a forming guide G having the contact or guide surface 162 of flat, planar form in a truly horizontal plane. Thus the follower pin 62 of a cutterhead and spindle assembly 60 moves over and across this planar guide surface 162 under the control of a pantograph linkage 50 as the forming guide G is fed downwardly under the control of a downfeed cam 129. However, my invention contemplates and includes the use of forming guides having contoured guide surfaces, either concave or convex, or other suitable or desired contour, for the purpose of obtaining a 3-dimensional effect in the milling operations. With such a contoured forming guide, in addition to the downfeed of the forming guide by a downfeed cam, the cutter spindle through a unit 60 in which it may be included, is caused to follow the contour of the guide surface of a forming guide and to thus be vertically raised and lowered in accordance with the contour of that surface and the portions thereof being engaged by the follower pin 62 of a unit 60 as that unit is universally laterally displaced through a pantograph linkage 50 and tracer arm 55 under the control and dictation of a master unit.

While I have disclosed pantograph milling units P1, P2, P3, and P4 of the 2-dimensional type in the example machine, it is intended to, and the invention includes, use of pantograph milling units of the 3-dimensional type for performing milling operations in three dimensions, such 3-dimensional pantograph units being exemplified, for example, from among other types adapted for this purpose in U.S. Patents 2,128,611 and 2,161,709.

Each of the downfeed mechanisms of each of the pantograph milling units P1, P2, P3, and P4 includes a limit switch interlocked in the circuit which controls the downfeed motor for that mechanism. In the example machine the limit switches in the circuits for the downfeed motors FM1, FM2, FM3, and FM4 of each of the pantograph milling units, are identified by the reference characters 7LS, 8LS, 9LS, and 10LS, respectively. As the downfeed mechanisms and the limit switches 7LS, 8LS, 9LS, and 10LS, and the actuating mechanisms for such switches are all identical, it will suffice to describe in detail only the limit switch 10LS for the downfeed motor FM4 of the downfeed mechanism of the pantograph milling unit P4. Referring now to FIGS. 10, 11, and 12, in particular, the carriage 144 mounts and carries an arm 170 which extends laterally outwardly from one side thereof and which is vertically displaced upwardly and downwardly with the upward and downward feed movements of the carriage. At its outer end the arm 170 adjustably mounts therein an abutment pin 171 in vertically disposed position with its upper end being provided with the abutment head 172. A bracket structure 173 extends horizontally and laterally outwardly from the supporting base frame structure 120 in position located above and generally parallel with the arm 170. A crank member 174 is pivotally mounted on the bracket 173 by a pivot pin 175 with this crank member 174 having the long arm 176 thereof disposed in vertically upwardly extending position above and in general vertical alignment with the abutment pin 172 in position for engagement of the lower end 177 thereof with the abutment head 172 of pin 171. The bracket 173 mounts therein a limit pin 178 positioned at the inner side of arm 176 adjacent the upper end thereof for limiting inward swinging of the crank member 174.

The limit switch 10LS, which may, as in this example, be of the microswitch type, is mounted and secured in position on the bracket 173 at the outer side of crank member 174 and is provided with an inwardly extending, horizontally disposed actuator pin or plunger 179 adapted to be engaged by the adjacent upper end of arm 176 of crank member 174 when that member is swung by engagement with abutment pin 171 on upward displacement of that pin with carriage 144. The limit switch

- 10LS and the identical limit switches 7LS, 8LS, and 9LS of the downfeed mechanisms of the pantograph milling units P1, P2, and P3, respectively, are of the normally closed type, that is, when a switch plunger 5 of 179 of any one of these limit switches is in its outwardly projected position, the switch is closed to thus close a circuit therethrough into which the switch is connected. When, however, switch plunger 179 of one of these 10 limit switches is pressed inwardly by outward rocking 15 of the crank member 174 the switch is opened to thereby open a circuit therethrough in which the switch is connected. If desired, as in the present example, a signal light 180 and mounting housing therefor 181, is mounted on the upper end of each of these limit switches 7LS, 8LS, 9LS, and 10LS and is connected into any usual circuit 20 therefor (not shown) controlled from the limit switch with which associated in order to give a visual signal to the operator of the condition of such limit switch and the downfeed motor which it controls. 25 Thus, in the operation of the example machine, upon completion of the downfeed cycles of the downfeed cams 129, all of the carriages 144 with their switch actuating arms 170 move upwardly to operate the limit switches 7LS, 8LS, 9LS and 10LS to open the circuits 30 to downfeed motors FM1, FM2, FM3, and FM4 to stop cutter spindle downfeeding. 35 While a cutter spindle downfeed mechanism of the powered, bell cam type is shown as incorporated in the example machine, the invention is not limited to this particular type, construction and functioning of downfeed mechanism, as various other types of cutter spindle downfeed, powered or manual, may be embodied in a machine organization of the invention as may be found desirable or expedient in any particular instance. 40 Similarly, while the downfeed mechanism of this example is powered by an electric motor, it is to be understood that a downfeed mechanism employed in an organization of the invention is not limited to any particular form or type of power, as a feed mechanism may be operated by pressure fluid, by spring forces, mechanically or manually within the basic combination, integration and organization of a machine embodying the invention and the various features thereof. Hence, the expression or designation downfeed or feed mechanism is used here- 45 in to include and designate not only the specific downfeed mechanism of this example, but any other downfeed mechanism which meets the combinational and functional requirements of the broad concept of the invention. 50

Power Circuits

- Referring now to FIG. 13 of the accompanying drawings, the motors SM1, SM2, SM3, SM4, TM, MM1, MM2, MM3, MM4, CM, FM1, FM2, FM3, and FM4 55 are supplied with electric power from any suitable source (not shown), say 3-phase, 220 volt A.C. current by the power lines L1, L2, and L3 into which the several motors of the machine are connected. The cutter spindle motors SM1, SM2, SM3, and SM4 are connected by power lines 13T1, 13T2, and 13T3 leading from lines L1, L2, and L3, to the motor SM3 with the lines 11T1, 11T2, and 11T3 branching therefrom to motor SM1; lines 12T1, 12T2, and 12T3 branching therefrom to motor SM2; lines 14T1, 14T2, and 14T3 branching therefrom to motor SM4; and lines 15T1, 15T2, and 15T3 branching 60 therefrom to motor TM. Powered master motor MM1 is connected with power lines L1, L2, and L3 by lines 2T1, 2T2, and 2T3; master motor MM2 by lines 3T1, 3T2, and 3T3; master motor MM3 by lines 4T1, 4T2, and 4T3; and master motor MM4 by lines 5T1, 5T2, and 5T3. The coolant motor CM is connected with power lines L1, L2, and L3 by lines 6T1, 6T2, and 6T3. The cutter spindle feed motors FM1, FM2, FM3, and FM4 are connected with power lines L1, L2, and L3 by lines 7T1, 7T2, and 7T3; lines 8T1, 8T2, and 75 9T3 by lines 8T1, 8T2, and 8T3; lines 9T1, 9T2, and 9T3 by lines 10T1, 10T2, and 10T3; lines 11T1, 11T2, and 11T3 by lines 12T1, 12T2, and 12T3; lines 13T1, 13T2, and 13T3 by lines 14T1, 14T2, and 14T3; lines 15T1, 15T2, and 15T3 by lines 16T1, 16T2, and 16T3; lines 17T1, 17T2, and 17T3 by lines 18T1, 18T2, and 18T3; lines 19T1, 19T2, and 19T3 by lines 20T1, 20T2, and 20T3; lines 21T1, 21T2, and 21T3 by lines 22T1, 22T2, and 22T3; lines 23T1, 23T2, and 23T3 by lines 24T1, 24T2, and 24T3; lines 25T1, 25T2, and 25T3 by lines 26T1, 26T2, and 26T3; lines 27T1, 27T2, and 27T3 by lines 28T1, 28T2, and 28T3; lines 29T1, 29T2, and 29T3 by lines 30T1, 30T2, and 30T3; lines 31T1, 31T2, and 31T3 by lines 32T1, 32T2, and 32T3; lines 33T1, 33T2, and 33T3 by lines 34T1, 34T2, and 34T3; lines 35T1, 35T2, and 35T3 by lines 36T1, 36T2, and 36T3; lines 37T1, 37T2, and 37T3 by lines 38T1, 38T2, and 38T3; lines 39T1, 39T2, and 39T3 by lines 40T1, 40T2, and 40T3; lines 41T1, 41T2, and 41T3 by lines 42T1, 42T2, and 42T3; lines 43T1, 43T2, and 43T3 by lines 44T1, 44T2, and 44T3; lines 45T1, 45T2, and 45T3 by lines 46T1, 46T2, and 46T3; lines 47T1, 47T2, and 47T3 by lines 48T1, 48T2, and 48T3; lines 49T1, 49T2, and 49T3 by lines 50T1, 50T2, and 50T3; lines 51T1, 51T2, and 51T3 by lines 52T1, 52T2, and 52T3; lines 53T1, 53T2, and 53T3 by lines 54T1, 54T2, and 54T3; lines 55T1, 55T2, and 55T3 by lines 56T1, 56T2, and 56T3; lines 57T1, 57T2, and 57T3 by lines 58T1, 58T2, and 58T3; lines 59T1, 59T2, and 59T3 by lines 60T1, 60T2, and 60T3; lines 61T1, 61T2, and 61T3 by lines 62T1, 62T2, and 62T3; lines 63T1, 63T2, and 63T3 by lines 64T1, 64T2, and 64T3; lines 65T1, 65T2, and 65T3 by lines 66T1, 66T2, and 66T3; lines 67T1, 67T2, and 67T3 by lines 68T1, 68T2, and 68T3; lines 69T1, 69T2, and 69T3 by lines 70T1, 70T2, and 70T3; lines 71T1, 71T2, and 71T3 by lines 72T1, 72T2, and 72T3; lines 73T1, 73T2, and 73T3 by lines 74T1, 74T2, and 74T3; lines 75T1, 75T2, and 75T3 by lines 76T1, 76T2, and 76T3; lines 77T1, 77T2, and 77T3 by lines 78T1, 78T2, and 78T3; lines 79T1, 79T2, and 79T3 by lines 80T1, 80T2, and 80T3; lines 81T1, 81T2, and 81T3 by lines 82T1, 82T2, and 82T3; lines 83T1, 83T2, and 83T3 by lines 84T1, 84T2, and 84T3; lines 85T1, 85T2, and 85T3 by lines 86T1, 86T2, and 86T3; lines 87T1, 87T2, and 87T3 by lines 88T1, 88T2, and 88T3; lines 89T1, 89T2, and 89T3 by lines 90T1, 90T2, and 90T3; lines 91T1, 91T2, and 91T3 by lines 92T1, 92T2, and 92T3; lines 93T1, 93T2, and 93T3 by lines 94T1, 94T2, and 94T3; lines 95T1, 95T2, and 95T3 by lines 96T1, 96T2, and 96T3; lines 97T1, 97T2, and 97T3 by lines 98T1, 98T2, and 98T3; lines 99T1, 99T2, and 99T3 by lines 100T1, 100T2, and 100T3; lines 101T1, 101T2, and 101T3 by lines 102T1, 102T2, and 102T3; lines 103T1, 103T2, and 103T3 by lines 104T1, 104T2, and 104T3; lines 105T1, 105T2, and 105T3 by lines 106T1, 106T2, and 106T3; lines 107T1, 107T2, and 107T3 by lines 108T1, 108T2, and 108T3; lines 109T1, 109T2, and 109T3 by lines 110T1, 110T2, and 110T3; lines 111T1, 111T2, and 111T3 by lines 112T1, 112T2, and 112T3; lines 113T1, 113T2, and 113T3 by lines 114T1, 114T2, and 114T3; lines 115T1, 115T2, and 115T3 by lines 116T1, 116T2, and 116T3; lines 117T1, 117T2, and 117T3 by lines 118T1, 118T2, and 118T3; lines 119T1, 119T2, and 119T3 by lines 120T1, 120T2, and 120T3; lines 121T1, 121T2, and 121T3 by lines 122T1, 122T2, and 122T3; lines 123T1, 123T2, and 123T3 by lines 124T1, 124T2, and 124T3; lines 125T1, 125T2, and 125T3 by lines 126T1, 126T2, and 126T3; lines 127T1, 127T2, and 127T3 by lines 128T1, 128T2, and 128T3; lines 129T1, 129T2, and 129T3 by lines 130T1, 130T2, and 130T3; lines 131T1, 131T2, and 131T3 by lines 132T1, 132T2, and 132T3; lines 133T1, 133T2, and 133T3 by lines 134T1, 134T2, and 134T3; lines 135T1, 135T2, and 135T3 by lines 136T1, 136T2, and 136T3; lines 137T1, 137T2, and 137T3 by lines 138T1, 138T2, and 138T3; lines 139T1, 139T2, and 139T3 by lines 140T1, 140T2, and 140T3; lines 141T1, 141T2, and 141T3 by lines 142T1, 142T2, and 142T3; lines 143T1, 143T2, and 143T3 by lines 144T1, 144T2, and 144T3; lines 145T1, 145T2, and 145T3 by lines 146T1, 146T2, and 146T3; lines 147T1, 147T2, and 147T3 by lines 148T1, 148T2, and 148T3; lines 149T1, 149T2, and 149T3 by lines 150T1, 150T2, and 150T3; lines 151T1, 151T2, and 151T3 by lines 152T1, 152T2, and 152T3; lines 153T1, 153T2, and 153T3 by lines 154T1, 154T2, and 154T3; lines 155T1, 155T2, and 155T3 by lines 156T1, 156T2, and 156T3; lines 157T1, 157T2, and 157T3 by lines 158T1, 158T2, and 158T3; lines 159T1, 159T2, and 159T3 by lines 160T1, 160T2, and 160T3; lines 161T1, 161T2, and 161T3 by lines 162T1, 162T2, and 162T3; lines 163T1, 163T2, and 163T3 by lines 164T1, 164T2, and 164T3; lines 165T1, 165T2, and 165T3 by lines 166T1, 166T2, and 166T3; lines 167T1, 167T2, and 167T3 by lines 168T1, 168T2, and 168T3; lines 169T1, 169T2, and 169T3 by lines 170T1, 170T2, and 170T3; lines 171T1, 171T2, and 171T3 by lines 172T1, 172T2, and 172T3; lines 173T1, 173T2, and 173T3 by lines 174T1, 174T2, and 174T3; lines 175T1, 175T2, and 175T3 by lines 176T1, 176T2, and 176T3; lines 177T1, 177T2, and 177T3 by lines 178T1, 178T2, and 178T3; lines 179T1, 179T2, and 179T3 by lines 180T1, 180T2, and 180T3; lines 181T1, 181T2, and 181T3 by lines 182T1, 182T2, and 182T3; lines 183T1, 183T2, and 183T3 by lines 184T1, 184T2, and 184T3; lines 185T1, 185T2, and 185T3 by lines 186T1, 186T2, and 186T3; lines 187T1, 187T2, and 187T3 by lines 188T1, 188T2, and 188T3; lines 189T1, 189T2, and 189T3 by lines 190T1, 190T2, and 190T3; lines 191T1, 191T2, and 191T3 by lines 192T1, 192T2, and 192T3; lines 193T1, 193T2, and 193T3 by lines 194T1, 194T2, and 194T3; lines 195T1, 195T2, and 195T3 by lines 196T1, 196T2, and 196T3; lines 197T1, 197T2, and 197T3 by lines 198T1, 198T2, and 198T3; lines 199T1, 199T2, and 199T3 by lines 200T1, 200T2, and 200T3; lines 201T1, 201T2, and 201T3 by lines 202T1, 202T2, and 202T3; lines 203T1, 203T2, and 203T3 by lines 204T1, 204T2, and 204T3; lines 205T1, 205T2, and 205T3 by lines 206T1, 206T2, and 206T3; lines 207T1, 207T2, and 207T3 by lines 208T1, 208T2, and 208T3; lines 209T1, 209T2, and 209T3 by lines 210T1, 210T2, and 210T3; lines 211T1, 211T2, and 211T3 by lines 212T1, 212T2, and 212T3; lines 213T1, 213T2, and 213T3 by lines 214T1, 214T2, and 214T3; lines 215T1, 215T2, and 215T3 by lines 216T1, 216T2, and 216T3; lines 217T1, 217T2, and 217T3 by lines 218T1, 218T2, and 218T3; lines 219T1, 219T2, and 219T3 by lines 220T1, 220T2, and 220T3; lines 221T1, 221T2, and 221T3 by lines 222T1, 222T2, and 222T3; lines 223T1, 223T2, and 223T3 by lines 224T1, 224T2, and 224T3; lines 225T1, 225T2, and 225T3 by lines 226T1, 226T2, and 226T3; lines 227T1, 227T2, and 227T3 by lines 228T1, 228T2, and 228T3; lines 229T1, 229T2, and 229T3 by lines 230T1, 230T2, and 230T3; lines 231T1, 231T2, and 231T3 by lines 232T1, 232T2, and 232T3; lines 233T1, 233T2, and 233T3 by lines 234T1, 234T2, and 234T3; lines 235T1, 235T2, and 235T3 by lines 236T1, 236T2, and 236T3; lines 237T1, 237T2, and 237T3 by lines 238T1, 238T2, and 238T3; lines 239T1, 239T2, and 239T3 by lines 240T1, 240T2, and 240T3; lines 241T1, 241T2, and 241T3 by lines 242T1, 242T2, and 242T3; lines 243T1, 243T2, and 243T3 by lines 244T1, 244T2, and 244T3; lines 245T1, 245T2, and 245T3 by lines 246T1, 246T2, and 246T3; lines 247T1, 247T2, and 247T3 by lines 248T1, 248T2, and 248T3; lines 249T1, 249T2, and 249T3 by lines 250T1, 250T2, and 250T3; lines 251T1, 251T2, and 251T3 by lines 252T1, 252T2, and 252T3; lines 253T1, 253T2, and 253T3 by lines 254T1, 254T2, and 254T3; lines 255T1, 255T2, and 255T3 by lines 256T1, 256T2, and 256T3; lines 257T1, 257T2, and 257T3 by lines 258T1, 258T2, and 258T3; lines 259T1, 259T2, and 259T3 by lines 260T1, 260T2, and 260T3; lines 261T1, 261T2, and 261T3 by lines 262T1, 262T2, and 262T3; lines 263T1, 263T2, and 263T3 by lines 264T1, 264T2, and 264T3; lines 265T1, 265T2, and 265T3 by lines 266T1, 266T2, and 266T3; lines 267T1, 267T2, and 267T3 by lines 268T1, 268T2, and 268T3; lines 269T1, 269T2, and 269T3 by lines 270T1, 270T2, and 270T3; lines 271T1, 271T2, and 271T3 by lines 272T1, 272T2, and 272T3; lines 273T1, 273T2, and 273T3 by lines 274T1, 274T2, and 274T3; lines 275T1, 275T2, and 275T3 by lines 276T1, 276T2, and 276T3; lines 277T1, 277T2, and 277T3 by lines 278T1, 278T2, and 278T3; lines 279T1, 279T2, and 279T3 by lines 280T1, 280T2, and 280T3; lines 281T1, 281T2, and 281T3 by lines 282T1, 282T2, and 282T3; lines 283T1, 283T2, and 283T3 by lines 284T1, 284T2, and 284T3; lines 285T1, 285T2, and 285T3 by lines 286T1, 286T2, and 286T3; lines 287T1, 287T2, and 287T3 by lines 288T1, 288T2, and 288T3; lines 289T1, 289T2, and 289T3 by lines 290T1, 290T2, and 290T3; lines 291T1, 291T2, and 291T3 by lines 292T1, 292T2, and 292T3; lines 293T1, 293T2, and 293T3 by lines 294T1, 294T2, and 294T3; lines 295T1, 295T2, and 295T3 by lines 296T1, 296T2, and 296T3; lines 297T1, 297T2, and 297T3 by lines 298T1, 298T2, and 298T3; lines 299T1, 299T2, and 299T3 by lines 300T1, 300T2, and 300T3; lines 301T1, 301T2, and 301T3 by lines 302T1, 302T2, and 302T3; lines 303T1, 303T2, and 303T3 by lines 304T1, 304T2, and 304T3; lines 305T1, 305T2, and 305T3 by lines 306T1, 306T2, and 306T3; lines 307T1, 307T2, and 307T3 by lines 308T1, 308T2, and 308T3; lines 309T1, 309T2, and 309T3 by lines 310T1, 310T2, and 310T3; lines 311T1, 311T2, and 311T3 by lines 312T1, 312T2, and 312T3; lines 313T1, 313T2, and 313T3 by lines 314T1, 314T2, and 314T3; lines 315T1, 315T2, and 315T3 by lines 316T1, 316T2, and 316T3; lines 317T1, 317T2, and 317T3 by lines 318T1, 318T2, and 318T3; lines 319T1, 319T2, and 319T3 by lines 320T1, 320T2, and 320T3; lines 321T1, 321T2, and 321T3 by lines 322T1, 322T2, and 322T3; lines 323T1, 323T2, and 323T3 by lines 324T1, 324T2, and 324T3; lines 325T1, 325T2, and 325T3 by lines 326T1, 326T2, and 326T3; lines 327T1, 327T2, and 327T3 by lines 328T1, 328T2, and 328T3; lines 329T1, 329T2, and 329T3 by lines 330T1, 330T2, and 330T3; lines 331T1, 331T2, and 331T3 by lines 332T1, 332T2, and 332T3; lines 333T1, 333T2, and 333T3 by lines 334T1, 334T2, and 334T3; lines 335T1, 335T2, and 335T3 by lines 336T1, 336T2, and 336T3; lines 337T1, 337T2, and 337T3 by lines 338T1, 338T2, and 338T3; lines 339T1, 339T2, and 339T3 by lines 340T1, 340T2, and 340T3; lines 341T1, 341T2, and 341T3 by lines 342T1, 342T2, and 342T3; lines 343T1, 343T2, and 343T3 by lines 344T1, 344T2, and 344T3; lines 345T1, 345T2, and 345T3 by lines 346T1, 346T2, and 346T3; lines 347T1, 347T2, and 347T3 by lines 348T1, 348T2, and 348T3; lines 349T1, 349T2, and 349T3 by lines 350T1, 350T2, and 350T3; lines 351T1, 351T2, and 351T3 by lines 352T1, 352T2, and 352T3; lines 353T1, 353T2, and 353T3 by lines 354T1, 354T2, and 354T3; lines 355T1, 355T2, and 355T3 by lines 356T1, 356T2, and 356T3; lines 357T1, 357T2, and 357T3 by lines 358T1, 358T2, and 358T3; lines 359T1, 359T2, and 359T3 by lines 360T1, 360T2, and 360T3; lines 361T1, 361T2, and 361T3 by lines 362T1, 362T2, and 362T3; lines 363T1, 363T2, and 363T3 by lines 364T1, 364T2, and 364T3; lines 365T1, 365T2, and 365T3 by lines 366T1, 366T2, and 366T3; lines 367T1, 367T2, and 367T3 by lines 368T1, 368T2, and 368T3; lines 369T1, 369T2, and 369T3 by lines 370T1, 370T2, and 370T3; lines 371T1, 371T2, and 371T3 by lines 372T1, 372T2, and 372T3; lines 373T1, 373T2, and 373T3 by lines 374T1, 374T2, and 374T3; lines 375T1, 375T2, and 375T3 by lines 376T1, 376T2, and 376T3; lines 377T1, 377T2, and 377T3 by lines 378T1, 378T2, and 378T3; lines 379T1, 379T2, and 379T3 by lines 380T1, 380T2, and 380T3; lines 381T1, 381T2, and 381T3 by lines 382T1, 382T2, and 382T3; lines 383T1, 383T2, and 383T3 by lines 384T1, 384T2, and 384T3; lines 385T1, 385T2, and 385T3 by lines 386T1, 386T2, and 386T3; lines 387T1, 387T2, and 387T3 by lines 388T1, 388T2, and 388T3; lines 389T1, 389T2, and 389T3 by lines 390T1, 390T2, and 390T3; lines 391T1, 391T2, and 391T3 by lines 392T1, 392T2, and 392T3; lines 393T1, 393T2, and 393T3 by lines 394T1, 394T2, and 394T3; lines 395T1, 395T2, and 395T3 by lines 396T1, 396T2, and 396T3; lines 397T1, 397T2, and 397T3 by lines 398T1, 398T2, and 398T3; lines 399T1, 399T2, and 399T3 by lines 400T1, 400T2, and 400T3; lines 401T1, 401T2, and 401T3 by lines 402T1, 402T2, and 402T3; lines 403T1, 403T2, and 403T3 by lines 404T1, 404T2, and 404T3; lines 405T1, 405T2, and 405T3 by lines 406T1, 406T2, and 406T3; lines 407T1, 407T2, and 407T3 by lines 408T1, 408T2, and 408T3; lines 409T1, 409T2, and 409T3 by lines 410T1, 410T2, and 410T3; lines 411

8T3; lines 9T1, 9T2, and 9T3; and lines 10T1, 10T2, and 10T3, respectively.

Power lines L1 and L2 lead and are connected to the primary winding of the master power transformer 1PT, from the secondary of which transformer current is supplied to the control circuit network of the machine by the circuit lines L32 and L33, as shown in FIG. 14. The power transformer 1PT may be considered to step down the 220 volt, A.C. power current supplied to the primary thereof, to a 110 volt, A.C. control current in the secondary of the transformer.

The control circuits for the particular machine of this example include the lines L32 and L33 from the secondary of the master power transformer 1PT, across which lines there is connected a circuit line L17 in which there is connected a contactor 19M having the normally open sets of contacts 10M' in the power lines 6T1, 6T2, and 6T3 to the coolant motor CM. A coolant motor switch 200 is connected in circuit line L17 for manual operation by an operator to open and close the circuit through contactor 19M and its sets of contacts in the power lines to the coolant motor CM for controlling operation of that motor. This coolant motor switch 200 is preferably located on a suitable control box or panel CB positioned adjacent the operator station at the forward side of the machine.

A circuit line L18 is connected across lines L32 and L33 and has connected therein a master stop switch 201, a stop switch 202, and a start switch 203. A shunt or bridge line L18' is connected around the start switch 203. A contactor 5M is connected in line L18 between start switch 203 and line L33. A circuit line L8 is connected to circuit line L18 between the master stop switch 201 and the stop switch 202, while a circuit line L15 is connected to circuit line L33 as a continuation of the latter with the stop switch 202, the start switch 203, and the contactor 5M connected in circuit line L18 across and between the circuit lines L8 and L33—L15. The contactor 5M provides a set of normally open contacts 5M' connected in line L8 between the circuit line L18 and a line L16 connected across lines L8 and L15.

The circuit line L16 connected across circuit lines L8 and L15 has connected therein a normally open cycle reset switch 204. A circuit relay 1CR is also connected in line L16 between the cycle reset switch 204 and line L15. This cycle reset circuit line L16 is connected into line L8 at a location to place the set of normally open contacts 5M' between it and the circuit line L18.

A circuit line L9 is connected across circuit lines L8 and L15 and has connected therein an index switch 205 which is normally closed. A normally open limit switch 1LS is connected in circuit line L9 between index switch 205 and line L15, this switch 1LS being adapted to be automatically operated in automatic cycling of the machine from the index table T in a manner to be herein-after described. A set of normally closed, late opening contacts TR' of a time relay are connected in circuit line L9 between the switch 1LS and line L15 and a circuit relay 2CR is also connected in line L9 between the relay contacts TR' and line L15.

A circuit line L5 is connected across circuit lines L8 and L15 and includes therein a normally open set of contacts 206 adapted to be closed by the index switch 205 upon actuation of that switch to open the circuit line L9. An index solenoid 207 is connected in circuit line L5 between the switch contacts 206 and line L15. This solenoid 207 is normally deenergized and, as hereinbefore explained, controls and initiates the operation of the indexing mechanism to index table T through an index step. Normally open limit switches 2LS', 3LS', 4LS', and 5LS' are connected in circuit line L5 in that order between circuit line L8 and the index solenoid 207. These normally open limit switches are suitably mechanically interlocked with the powered master and milling cycle con-

trolling limit switches 2LS, 3LS, 4LS, and 5LS, as will be explained hereinafter.

A circuit line L11 is connected across lines L8 and L15 and has connected therein the normally closed limit switch 2LS of the powered master unit M1 of pantograph milling unit P1. A contactor 6M is connected in circuit line L11 between limit switch 2LS and line L15 and a contactor 11M is connected into line L11 in parallel with contactor 6M by a circuit line L44. The contactor 6M includes the sets of normally open contacts 6M' connected in the power lines 2T1, 2T2, and 2T3 to the master motor MM1 for controlling operation of that motor. The contactor 11M includes the sets of normally open contacts 11M' connected in the power lines 7T1, 7T2, and 7T3 to the cutter spindle downfeed motor FM1 for opening and closing the circuits to that motor.

The normally closed limit switch 7LS for the driving motor FM1 for the downfeed mechanism of the pantograph milling unit P1 is connected in parallel with the limit switch 2LS in line L11 by the line L48; this limit switch 7LS being, like limit switch 2LS, of the normally closed type. A line L52 connects lines L48 and L11 between the limit switches 2LS and 7LS and the point of connection of line L48 into line L11 located between switch 2LS and contactor 6M. The circuit relay 1CR in line L16 includes a set of normally open contacts 1CR' in line L11 between line L52 and the point of connection of line L48 into line L11. The contactor 6M includes a set of normally open contacts 6M' in line L48 between line L52 and the point of connection of L48 into line L11 between switch 2LS and contactor 6M.

A circuit line L12 is connected across lines L8 and L15 and has connected therein the normally closed limit switch 3LS of the powered master unit M2 of pantograph milling unit P2. A contactor 7M is connected in circuit line L12 between limit switch 3LS and line L15 and a contactor 12M is connected into line L12 in parallel with contactor 7M by a circuit line L45. The contactor 7M includes the sets of normally open contacts 7M' in the power lines 3T1, 3T2, and 3T3 to the master motor MM2 for opening and closing the circuits to that motor. The contactor 12M includes the sets of normally open contacts 12M' in the power lines 8T1, 8T2, and 8T3 to the cutter spindle downfeed motor FM2 for opening and closing the circuits to that motor.

The normally closed limit switch 8LS for the driving motor FM2 for the downfeed mechanism of the pantograph milling unit P2 is connected in parallel with the limit switch 3LS in line L12 by the line L49. A line L53 connects lines L49 and L12 between the limit switches 3LS and 8LS and the point of connection of line L49 into line L12 located between switch 3LS and contactor 7M. The circuit relay 1CR in line L16 also includes a set of normally open contacts 1CR in line L12 between line L53 and the point of connection of line L49 into line L12. The contactor 7M includes a set of normally open contacts 7M' in line L49 between line L53 and the point of connection of line L49 into line L12 between switch 3LS and the contactor 7M.

A circuit line L14 is connected across lines L8 and L15 and has connected therein the normally closed limit switch 4LS of the powered master unit M3 of pantograph milling unit P3. A contactor 8M is connected in circuit line L14 between limit switch 4LS and line L15 and a contactor 14M is connected into line L14 in parallel with contactor 8M by a circuit line L46. The contactor 8M includes the sets of normally open contacts 8M' in lines 4T1, 4T2, and 4T3 to the master motor MM3 for opening and closing such power lines for controlling the operation of the motor MM3. The contactor 14M includes the sets of the normally open contacts 14M' in the power lines 9T1, 9T2, and 9T3 to the cutter spindle downfeed motor FM3 for opening and closing the circuits to that motor.

The normally closed limit switch 9LS for the driving

motor FM3 for the downfeed mechanism of the pantograph milling unit P1 is connected in parallel with the limit switch 4LS in line L14 by the line L50. A line L54 connects lines L50 and L14 between the limit switches 4LS and 9LS and the point of connection of line L50 into line L14 at a point between limit switch 4LS and the contactor 8M. The circuit relay 1CR also includes a set of normally open contacts 1CR' in line L14 between line 54 and the point of connection of line 50 into the line L14. The contactor 8M also includes a set of normally open contacts 8M' in line L50 between line L54 and the point of connection of line L50 into the line L14 between limit switches 4LS and the contactor 8M.

A circuit line L20 is connected across line L8 and line L15 and has connected therein the normally closed limit switch 5LS of the powered master unit M4 of pantograph unit P4. A contactor 9M is connected in circuit line L20 between limit switch 5LS and line L15 and a contactor 15M is connected into line L20 in parallel with contactor 9M by a circuit line L47. The contactor 9M includes the sets of normally open contacts 9M' in the power lines 5T1, 5T2, and 5T3 to the master motor MM4 for opening and closing such power lines for controlling operation of that motor. The contactor 15M includes the sets of normally open contacts 15M' in the power lines 10T1, 10T2, and 10T3 to the cutter spindle downfeed motor FM4 for opening and closing such power circuits to control the operation of that motor.

The normally closed limit switch 10LS for the drive motor FM4 for the downfeed mechanism of the pantograph milling unit P4 is connected in parallel with the limit switch 5LS in line L20 by the line L51. A line L55 connects lines L51 and line L20 between the limit switches 5LS and 10LS and the point of connection of line L51 into line L20 which is located between switch 5LS and the contactor 9M. The circuit relay 1CR in line L16 also includes another set of normally open contacts 1CR' in line L20 between line L53 and the point of connection of line L51 into the line L20.

The contactor 9M also includes a set of normally open contacts 9M' in line L51 between line L55 and the point of connection of line L51 into line L20 between the limit switch 5LS and the contactor 9M. A circuit line L10 is connected at one end into circuit line L9 between the limit switch 1LS and the set of normally closed—late opening contacts TR' in that line, and is connected at its opposite end by a circuit line L21 which is connected across line L10 and circuit line L15. A circuit line L9' is connected into line L9 between indexing switch 205 and the limit switch 1LS and shunts or bridges around the latter switch to and is connected into line L10. The circuit relay 2CR in the line L9 includes a set of normally open contacts 2CR' connected into line L9' between line L9 and the line L10.

A line L60 is connected between line L10 and line L11, being connected into the latter line between the point of connection of line L48 into line L11 and the point of connection of line L44 into line L11. The circuit relay 2CR in line L9 also includes a set of normally open contacts 2CR' connected into line L60. A circuit line L61 is connected between line L10 and line L12. Line L61 connects into line L10 at a point between the point of connection of line L60 into line L10 and the line L21. The circuit relay 2CR also includes a set of normally open contacts 2CR' connected into line L61. A line L62 is connected across lines L10 and L14. This line L62 is connected into line L10 at a point between line L61 and the line L21 and is connected into line L14 between the connection of line L50 into line L14 and connection of line L46 into line L14. The circuit relay 2CR also includes a set of normally open relay contacts 2CR' in the line L62. A line L63 is connected across lines L10 and L20. Line L63 is connected into line L10 at a point between line L62 and the line L21, while it is connected into the line L20 between the point of connection of line L51 into line L20 and the point of connection of line L47 into line L20. The circuit relay 2CR includes a set of normally open contacts 2CR' in line L63.

nection of line L51 into line L20 and the point of connection of line L47 into line L20. The circuit relay 2CR includes a set of normally open relay contacts 2CR' in the line L63.

5 A time relay TR is connected into the line L21 between lines L10 and L15 and when energized by the closing of a circuit therethrough activates its pair of normally closed contacts TR' in the line L9 so that after a pre-determined interval of time, the contacts TR' will open to open the circuit through line L9, for a purpose to be hereinafter described and explained.

10 As hereinbefore pointed out, the limit switches 2LS', 3LS', 4LS', and 5LS' are normally open switches and are mechanically interlocked with the limit switches 2LS, 3LS, 4LS, and 5LS, respectively, for the powered master units MM1, MM2, MM3, and MM4, these latter switches being normally closed. Hence, when switches 2LS, 3LS, 4LS, and 5LS are actuated to open positions by their respective powered master units, the normally open limit switches 2LS', 3LS', 4LS', and 5LS' are simultaneously closed to set-up and condition the indexing circuit line L5 for an indexing operation. Conversely, when the limit switches 2LS, 3LS, 4LS, and 5LS are returned from open to closed positions, the limit switches 2LS', 3LS', 4LS', and 5LS' in index circuit line L5 are simultaneously automatically returned to their normal open positions.

Operational Summary

30 With the example machine at rest and inactive the master stop switch 201 is open and all operating motors are stopped with the entire control circuit network cut off through the open contacts 5M' of the contactor 5M.

35 The index table T is at rest in position with four of the work stations, say, the stations W5, W6, W7, and W8 located at the operator station at the front of the machine and with the work stations W1, W2, W3, and W4 located in operating positions below the cutter spindles S1, S2, S3, and S4 of the pantograph milling units P1, P2, P3, and P4 which are positioned angularly spaced apart around the rear side of the index table. The operator then loads the work stations at the front of the machine with work pieces to be profile milled by the pantograph milling units upon indexing of the worktable to place the loaded work stations at operating positions beneath the several cutter spindles of the pantograph milling units.

40 In the at rest or inactive position of the machine the master units M1, M2, M3, and M4 will have automatically stopped at the end of the milling cycles which they have controlled and dictated with the tracers 90 thereof at what may be called their "home" positions in the master recesses 71, with the tracer arms 55 of the pantograph linkages 50 then in positions engaged against the operating plungers 118 of the limit switches 2LS, 3LS, therethrough and through their interlocks with the limit 4LS, and 5LS, respectively, to thus open the circuits therethrough and through their interlocks with the limit switches 2LS', 3LS', 4LS', and 5LS' in the index circuit to close the latter switches and thus condition the index circuit for indexing operation of the table T. Similarly, in such "at rest" position the downfeed cams of each of the downfeed mechanisms of the pantograph milling units P1, P2, P3, and P4 will be in positions with their respective downfeed carriages 144 in raised positions and with the limit switches 7LS, 8LS, 9LS, and 10LS actuated to open positions opening the circuits therethrough. Thus the circuits through the contactors 6M and 11M, 7M and 12M, 8M and 14M, and 9M and 15M will all be opened with these contactors inactivated.

45 In such "at rest" position of the machine with the master stop switch 201 open, the limit switch 1LS which is operated and controlled by the table indexing mechanism will also be open with the circuit through the relay 2CR open but with the index switch 205 closing the cir-

cuit line L9, the time relay contacts TR' in that circuit being also closed.

Similarly, the cycle reset switch 204 in the circuit line L16 will be open, thus inactivating the circuit through the relay 1CR. It is to be noted here that this cycle reset switch 204 is normally open and is not operated except under certain conditions of abnormal operation with the machine, as will be referred to and described hereinafter.

With the work stations at the front of the machine loaded with work pieces, in order to place the machine in condition for a cycle of profile milling operations thereon, the operator first closes the master stop switch 201, the stop switch 202 in circuit line L18 being also closed while the start switch 203 in that line is open. The operator then pushes the start switch 203 to closed position whereupon contactor 5M is activated and simultaneously closes its set of contacts 5M' in line L18' and its sets of contacts 5M' in the power lines to the spindle motors SM', SM2', SM3', SM4', and to the driving motor TM of the table indexing mechanism. Thus the cutter spindle motors and the indexing mechanism motor are set into operation preparatory to and ahead of the start of the cycle of milling operations of the machine.

After operating the start switch 203 and setting the spindle motors and the table indexing motor in operation, the operator then starts the profile milling cycle of operations by pressing the index switch 205 to position closing the index circuit line L5 in which the limit switches 2LS', 3LS', 4LS', and 5LS' have all been closed by their interlocks with the limit switches 2LS, 3LS, 4LS, and 5LS which have been actuated to open positions by the tracer arms 55 of the pantograph linkages of the pantograph milling units P1, P2, P3, and P4 when the powered master unit driven tracers 90 reached their "home" positions at the completion of the preceding milling cycles. Closing of the index circuit line L5 by switch 205 energizes the index solenoid 207 of the index table unit TU and thereby causes operation of unit TU to rotate table T to index the loaded work stations W5, W6, W7, and W8 to operating positions beneath the cutter spindles S4, S3, S2, and S1, respectively, of the pantograph milling units P4, P3, P2, and P1. The cutter spindles S1, S2, S3, and S4 of the pantograph milling units P1, P2, P3, and P4 are, of course, in their raised positions clear of the work pieces, having been so raised by the biasing springs 145 of the downfeed mechanisms at the completion of the downfeed cycles of the downfeed cams 129 which respectively control the cutter spindles.

As the indexing table T reaches its next position of index as a result of the operation of the indexing switch 205, and just preparatory to being locked in such position of index by the indexing mechanism of the unit TU, the limit switch 1LS is momentarily closed thereby. This momentary closing of the limit switch 1LS activates relay 2CR which thus closes the circuit line L9' around switch 1LS and simultaneously closes the sets of contacts 2CR' in the circuit lines L60, L61, L62, and L63, respectively, thus closing the circuits through the contactors 6M and 11M, 7M and 12M, 8M and 14M, and 9M and 15M. The closing of the above-identified contactors closes their respective sets of contacts in the power lines to the master unit motors MM1, MM2, MM3, and MM4 and to the downfeed mechanism motors FM1, FM2, FM3, and FM4, so that operation of these motors and of the powered masters and of the downfeed mechanisms is started.

With the closing of the circuit line L9' around the limit switch 1LS by the relay 2CR, the circuit through the time relay TR in line L21 is also closed. The normally closed set of contacts TR' of time relay TR in the index circuit line L9 is, however, of the delayed or late opening type so that such closed contacts hold the circuits through the motor controlling contactors closed for a sufficient interval of time to permit all of the tracer arms 55 of the pantograph linkages 50 of the pantograph milling units

to clear the limit switches 2LS, 3LS, 4LS, and 5LS and thereby permit such switches to close the circuits there-through. The closing of switches 2LS, 3LS, 4LS, and 5LS simultaneously opens the limit switches 2LS', 3LS', 4LS', and 5LS' in the index circuit line L5. When the circuit through line L9 is opened by the time relay contacts TR', the relay 2CR in line L9 is deenergized and its sets of contacts 2CR' in lines L9, L60, L61, L62, and L63 are opened. However, by the time this action takes place as a result of the opening of the time relay contacts TR', the tracer arms 55 have all moved from operating engagement with the limit switches 2LS, 3LS, 4LS, and 5LS so that these switches have returned to their normally closed positions and circuits have been established through the contactors 6M and 11M, 7M and 12M, 8M and 14M, and 9M and 15M and the powered master unit motors MM1, MM2, MM3, and MM4 are placed in operation on their milling cycles and the downfeed motors FM1, FM2, FM3, and FM4 are also placed in operation to feed the cutter spindles S1, S2, S3, and S4 into the work piece by the downfeed cams 129.

The profile milling operations of the cutter spindles S1, S2, S3, and S4 proceed through the milling cycles under the control and dictation of their respective master units M1, M2, M3, and M4 with progressive feed of the cutter spindles into the work pieces being controlled and determined by the respective downfeed cams 129. These operations continue until the tracers 90 have been driven completely around and through their respective pattern or master recesses 71, that is, until the tracers 90 reach their respective "home" positions. As the tracers 90 reach "home" positions, the tracer arms 55 engage the plungers 118 of the limit switches 2LS, 3LS, 4LS, and 5LS and thus open the circuits through the circuit lines L11, L12, L14, and L20, while at the same time, through the mechanical interlocks the limit switches 2LS', 3LS', 4LS', and 5LS' are closed and thus condition the index circuit line L5 for operation of the solenoid 207 of the table indexing mechanism upon closing of the index switch contacts 206. However, the circuits through the controlling contactors 6M and 11M, 7M and 12M, 8M and 14M, and 9M and 15M are not opened and rendered inactive by the initial opening of the limit switches 2LS, 3LS, 4LS, and 5LS, because circuits are maintained closed through these contactors by the downfeed mechanism limit switches 7LS, 8LS, 9LS, and 10LS until the several feed cams 129 have completed their cycles and the cutter spindle downfeed carriages 144 have displaced upwardly to thereby actuate limit switches 7LS, 8LS, 9LS, and 10LS to opened positions. When, however, the limit switches 7LS, 8LS, 9LS, and 10LS have been opened by the completion of the downfeeding cycles of the downfeed cams 129 (limit switches 2LS, 3LS, 4LS, and 5LS being open), all circuits to and through the contactors 6M and 11M, 7M and 12M, 8M and 14M, and 9M and 15M are opened and these contactors are inactivated with the result that their several sets of normally open but then closed contacts in the power lines to the master unit motors MM1, MM2, MM3, and MM4 and to the driving motors FM1, FM2, FM3, and FM4 of the downfeed mechanisms are stopped, and the milling cycles are completed with the machine then inactive and in condition for the next indexing step of worktable T and cycle of profile milling operations on the work pieces indexed by that table to operative milling positions at the pantograph milling units P1, P2, P3, and P4.

Upon the completion of a cycle of milling operations, with the downfeed mechanism of the example type disengaged in this particular machine embodiment, the cutter spindles S1, S2, S3, and S4 will have been automatically raised or elevated from milling positions in the work pieces by the spring loading of the cutterheads and cutter spindle units 90 as those units under that loading displace vertically upwardly in following the upwardly displacing forming guides G which rise under the control of the

downfeed cams 129 and the downfeed carriage biasing springs 145. Hence, upon the completion of the milling cycles and the automatic stopping thereof, the cutter spindles will also have been automatically raised to positions clear of the completed work pieces so that the worktable may be indexed to its next position without interference from or damage to the cutter spindles and cutters thereon and work pieces which have been engaged thereby in milling operations thereon.

During the preceding milling operations, of course, the work stations W1, W2, W3, and W4 were in position at the operator station at the front of the machine for loading with work pieces for performance thereon of the profile milling operations by the next cycle of such operations by the pantograph milling units P1, P2, P3, and P4. Thus, upon the completion of the preceding milling operations automatically by the machine, the operator then by actuating the index switch 205 to close the contacts 206 in the index circuit line L5, may cause the next indexing step of the table T to move the completed work pieces to the operator station for unloading and to move the loaded work stations to positions at the pantograph milling units P1, P2, P3, and P4 for the performance thereon of the milling operations under the control and dictation of the powered master units M1, M2, M3, and M4 and the power driven downfeed cams 129 of such units.

In the operation of the machine due to the inclusion in each of the powered master units M1, M2, M3, and M4 of the infinitely variable speed drive unit 38 and of the reversible coupling unit 38d, the rate of movement of each of the tracers 90 of a master unit is infinitely variable in either direction. Thus, the machine provides extreme flexibility and wide range of operation for each of the powered master units and the important requirement for the maintenance of the correct feed and speed on a cutter spindle for the most efficient operation of each of the pantograph milling units P1, P2, P3, and P4, can be fully met. In other words, each cutter spindle may be adjusted within fine limits in the rate of movement of feed thereof laterally through a work piece and the rate of feed thereof into the work piece. Due to the provision in each of the master power units for reversing the direction of movement of a tracer through and around its master recess, both climb and conventional milling can be carried out at any desired rate of speed.

With the machine of the example embodiment incorporating the various features of the invention, all of the pantograph milling units must be stopped and in their "home" positions, that is, the tracers 90 of such units, before the indexing table T can be indexed to its next position. This is carried out and made possible by the fact that the limit switches 2LS', 3LS', 4LS', and 5LS' must be closed in order to condition the indexing circuit for operation and that these limit switches can only be closed if and when the limit switches 2LS, 3LS, 4LS, and 5LS of the powered master units are all in open positions. And limit switches 2LS, 3LS, 4LS, and 5LS are normally closed switches and can only be opened by the tracer arms 55 of the pantograph milling units when those arms are positioned with the tracers 90 and the cutter spindles S1, S2, S3, and S4 controlled thereby, in "home" positions, that is, in positions at the completion of the milling cycles. Conversely, of course, it results from the foregoing that the pantograph milling units P1, P2, P3, and P4, including the powered master units M1, M2, M3, and M4, and the power driven cams 129 of the downfeed mechanisms, cannot be operated during the indexing cycle because their several controlling limit switches, as hereinbefore identified, are and must be open.

It is to be further noted that during indexing not only are the limit switches of the powered master units and the downfeed mechanisms open, but also the limit switch 1LS in circuit line L9 is open and therefore the relay 2CR in circuit line L9 is inactivated, so that its several sets of contacts 2CR' in the circuit lines L60, L61, L62, and

L63 are open, thus opening the circuits therethrough to the contactors 6M and 11M, 7M and 12M, 8M and 14M, and 9M and 15M.

If, for any reason during a cycle of milling operations, and before the completion thereof, an operator stops the milling operations by pressing the stop switch, it follows that the pantograph milling units will be put out of operation and will stop with the limit switches 2LS, 3LS, 4LS, and 5LS in closed positions but with limit switch 1LS open and with the various contactors and circuit relays inactive. Under such conditions it will be impossible to again start the interrupted milling cycles without operation of the cycle reset switch 204 and the circuit relay 1CR in the circuit line L16. In order to restart the interrupted cycle of milling operations, therefore, the operator closes the cycle reset switch 204 and thus closes the circuit through the relay 1CR which, in turn, simultaneously closes all of its sets of normally open contacts 1CR' in the circuit lines L11, L12, L14, and L20 in which the limit switches 2LS, 3LS, 4LS, and 5LS are already closed, so that the circuits are thereby completed through the contactors 6M and 11M, 7M and 12M, 8M and 14M, and 9M and 15M, and the pantograph milling units P1, P2, P3, and P4 start back into operation and proceed in the normal manner to complete the interrupted milling cycle.

In the example machine the index table unit TU is designed and set for index steps of the table T of 45° or 90°. Hence, this same type of machine having index steps of 45° can be toolled up to mill four (4) different operations on one work piece in which event the powered profile masters of the pantograph milling units P1, P2, P3, and P4 would each provide for and operate under the control of a different pattern or master. Thus it follows that with such machine so set up, the milling operations may cross each other, may require different diameter milling cutters, or may be at different depths of milling cut using a different cutter spindle controlling contour on the forming guides G of each of the downfeed mechanisms. And in this connection it is pointed out that an arrangement of the pantograph milling units P1, P2, P3, and P4 can be provided in which units P1 and P2 are located at 0° and 45° instead of 22½° and 67½°, as specifically shown in the example machine. Thus, by providing sixteen (16) work stations instead of the eight (8) work stations as specifically shown in this example, it is possible to profile mill four (4) work pieces of the same design at one time by adjusting the table indexing unit TU for index steps of 90° so that each milling cycle would produce four (4) completed work pieces. With the specific arrangement of the example machine of the invention as here presented, four (4) different operations may be profile milled at one time, or two (2) roughing and two (2) finishing operations may be profile milled at one time, or four (4) work pieces may be profile milled at one time with the same profile milling operation being performed by each of the pantograph milling units P1, P2, P3, and P4 on each work piece. It will be clear that in addition to the foregoing, various other combinations and permutations of work stations, indexing steps and pantograph milling units may be set up and utilized over a wide range of combinations, permutations and sequences in order to meet the requirements of the work pieces and profile milling operations to be performed thereon.

The powered master unit combinations and constructions, per se, and the powered master unit combinations with a milling or the like machine, and with the milling machine of the pantographic types of the herein disclosed example, are not claimed herein but are claimed in my copending U.S. patent application Serial No. 660,647, now Patent No. 2,866,391 issued Dec. 30, 1958, filed as a division of this parent application.

And the powered cutter spindle feeds and the combinations thereof in and with a milling or the like ma-

chine, and with the milling machine of the pantographic and powered master types of the example herein disclosed, are not claimed herein per se but are claimed in my aforesaid divisional application hereof, Serial No. 660,647.

It will also be evident that various other changes, modifications, variations, substitutions, eliminations and additions may be resorted to without departing from the broad spirit and scope of my invention, as defined in the claims hereto appended.

What I claim is:

1. In combination, a rotatable indexing table; a plurality of powered spindle units spaced from and spaced apart around the peripheral marginal portion of said indexing table; each of said powered spindle units including a rotary spindle driven thereby and mounted thereon in position over said indexing table with its axis generally normal to the plane of rotation of said indexing table for universal lateral movements thereover; each of said rotary spindles of each of said powered spindle units being also mounted for feeding movements toward and from said indexing table independently of and during lateral movements thereof; a powered master unit including a master therefor on each of said powered spindle units for universally laterally moving said rotary spindle of its said powered spindle unit under the control of said master through a predetermined cycle of operations; each of said powered master units including an electric driving motor therefor and a current supply circuit connected therewith; each of said powered spindle units having a powered spindle feed mechanism for its said rotary spindle including an electric driving motor and a current supply circuit connected therewith; a control circuit network connected with said supply circuits to said driving motors of said powered master units and with said supply circuits to said driving motors of said spindle feed mechanisms; said control circuit network being operable to effect opening and closing of said supply circuits to said driving motors of said spindle units and said driving motors of said spindle feed mechanisms; means mechanisms; means connected into said control circuit network operable by said powered master units upon completion of a predetermined cycle of lateral movements thereby of said rotary spindles of said powered spindle units to effect operation of said control circuit to open said supply circuits to said motors of said powered master units; and means connected into said control circuit network operable by said spindle feed mechanisms of said powered spindle units to effect operation of said control circuit network to open said supply circuits to said driving motors of said spindle feed mechanisms when said spindle feed mechanisms have completed predetermined feeding cycles of said rotary spindles of said powered spindle units.

2. In combination, a rotatable indexing table; a plurality of powered spindle units spaced from and spaced apart around said indexing table; each of said powered spindle units including a rotary spindle driven thereby and mounted thereon in position over said indexing table with its axis generally normal to the plane of rotation of said indexing table for universal lateral movements thereover; each of said rotary spindles being also mounted for feeding movements axially toward and from said indexing table independently of and during universal lateral movements thereof; a powered master unit on each of said powered spindle units for universally laterally moving said rotary spindle of its said powered spindle unit; each of said powered master units including an electric driving motor therefor and a current supply circuit connected with said driving motor; each of said powered spindle units having a powered spindle feed mechanism for feeding its said rotary spindle axially and including an electric driving motor and a current supply circuit connected therewith; a control circuit network connected with said supply circuits to said driving motors of said powered master units and with said supply circuits to said driving

motors of said spindle feed mechanisms; said control circuit network being operable to effect opening or closing of said supply circuits to said driving motors of said powered master units and said driving motors of said spindle feed mechanisms; a first means connected into said control circuit network operable by said powered master units upon the completion of predetermined cycles of operation thereof to condition said control circuit network for effecting opening of said supply circuits to said driving motors of said powered master units and said driving motors of said spindle feed mechanisms; and a second means connected into said control circuit network operable by said spindle feed mechanisms upon the completion of predetermined cycles of feeding thereby to effect operation of said control circuit network to complete the opening of said supply circuits to and stop operation of said driving motors of said powered master units and said powered spindle feed mechanisms when said control circuit network is conditioned for effecting the opening of said supply circuits by operation of said first means by said powered master units.

3. In combination, a rotatable indexing table; a plurality of powered spindle units spaced from and spaced apart around said indexing table; each of said powered spindle units including a rotary spindle driven thereby and mounted thereon in position over said indexing table with its axis generally normal to the plane of rotation of said indexing table for universal lateral movements thereover; each of said rotary spindles of each of said spindle units being also mounted for feeding movements axially toward and from said indexing table independently of and during universal lateral movements thereof over said indexing table; a powered master unit on each of said powered spindle units in operative connection with said rotary spindle of said unit for universally laterally moving said rotary spindle over said indexing table; each of said powered master units including an electric driving motor therefor and a current supply circuit connected with said driving motor; each of said powered spindle units having a powered spindle feed mechanism for feeding its said rotary spindle axially; each of said powered spindle feed mechanisms including an electric driving motor therefor and a current supply circuit connected with said driving motor; a control circuit network connected with said supply circuits to said driving motors of said powered master units and with said supply circuits to said driving motors of said spindle feed mechanisms; said control circuit network being operable to effect opening or closing of said supply circuits to said driving motors of said spindle feed mechanisms; a first set of normally closed limit switches in said control circuit network effecting when closed the operation of said network to close said supply circuits to said master unit driving motors and said spindle feed mechanism driving motors; said limit switches being operable to and held in open positions by said powered master units when the latter are in positions at the completion of their operating cycles and restoring to normal closed positions thereof when said powered master units move from their said positions at the completion of their operating cycles in starting the next operating cycles thereof; a second set of normally closed limit switches in said control circuit network operable by said spindle feed mechanisms to open positions when said spindle feed mechanisms are in their positions at the completion of their feeding cycles for effecting operation of said control circuit network to open said supply circuits to and stop operation of said driving motors only when said limit switches of said first set of limit switches are held in open position by said powered master units; said second set of limit switches restoring to normally closed positions when said spindle feed mechanisms move from the positions thereof at the completion of their feeding cycles; and said first set of limit switches being rendered ineffective to cause operation of said con-

trol circuit network to open said supply circuits to and stop operation of said driving motors of said powered master units and of said powered feed mechanisms when said limit switches of said second set of limit switches are closed.

4. In combination, a rotatable indexing table; powered mechanism for indexing said table step-by-step through successive positions of index; said powered indexing mechanism including an electric driving motor therefor and a current supply circuit connected with said driving motor; a plurality of powered spindle units spaced from and spaced apart around said indexing table; each of said powered spindle units including a rotary spindle driven thereby and mounted thereon in position over said indexing table with its axis generally normal to the plane of rotation of said indexing table for universal lateral movements thereover; each of said rotary spindles of each of said spindle units being also mounted for feeding movements axially toward and from said indexing table independently of and during universal lateral movements thereof over said indexing table; a powered master unit on each of said powered spindle units in operative connection with said rotary spindle of said spindle unit for universally laterally moving said rotary spindle over said indexing table; each of said powered master units including an electric driving motor therefor and a current supply circuit connected with said driving motor; each of said powered spindle units having a powered spindle feed mechanism for feeding its said rotary cutter spindle axially; each of said powered spindle feed mechanisms, including an electric driving motor therefor and a current supply circuit connected with said driving motor; a control circuit network connected with said current supply circuits to said driving motors of said powered indexing mechanism for said indexing table, said driving motors for said powered master units, and said driving motors of said spindle feed mechanisms; said control circuit network being selectively operable to effect opening or closing of said supply circuits to said driving motors; a first means connected in said control circuit network operable by said powered master units upon the completion of predetermined cycles of operation thereof to condition said control circuit network for effecting the opening of said supply circuits to said driving motors of said powered master units and said driving motors of said spindle feed mechanisms; a second means connected into said control circuit network operable by said spindle feed mechanisms upon the completion of predetermined cycles of feeding thereby to cause operation of said control circuit network to complete the opening of said supply circuits to and stop operation of said driving motors of said powered master units and said driving motors of said spindle feed mechanisms when said control circuit network is conditioned for the opening of said supply circuits by operation of said first means by said powered master units; and a third means connected into said control circuit network operable by said first means for effecting operation of said control circuit network to close said supply circuit to said driving motor of said indexing mechanism when said first means is operated by said powered master units to condition said control circuit network for effecting opening of said supply circuits to said driving motors of said powered master units and said driving motors of said spindle feed mechanisms and to cause said control circuit network to open said supply circuit to said driving motor of said indexing mechanism when said supply circuits to said driving motors of said powered master units and said powered spindle feed mechanisms are closed.

5. In the combination defined by claim 4, said third means in said control circuit network including a normally open limit switch interlocked with said first means in said control circuit network for closing by said first means when the latter is operated by said powered master units upon the completion of the operating cycles thereof for effecting opening of said supply circuits to said

driving motors of said powered master units and said powered spindle feed mechanisms and for opening when said supply circuits to said driving motors of said powered master units are closed by operation of said control circuit network by said first means.

6. In the combination defined by claim 4, a fourth means connected in said control circuit network operable by said indexing mechanism upon completion of an indexing operation for causing the operation of said control circuit network to close said current supply circuits to said driving motors of said powered master units to effect operation thereof to initiate the next operating cycles of said powered master units.

7. In the combination of claim 4, a time-controlled means connected in said control circuit network rendered operative by said indexing mechanism when the latter mechanism completes an indexing operation of said indexing table through an indexing step to close for a predetermined period of time the current supply circuits to said driving motors of said powered master units to effect operation of said master units while said current supply circuits are held open by the operation of said first means by said powered master units.

8. In combination, a rotatable indexing table; powered mechanism for indexing said table step-by-step through successive positions of indexing; said powered indexing mechanism including an electric driving motor therefor and a current supply circuit connected with said driving motor; a plurality of powered spindle units spaced from and spaced apart around said indexing table; each of said powered spindle units including a rotary spindle driven thereby and mounted thereon in position over said indexing table with its axis generally normal to the plane of rotation of said indexing table for universal lateral movements thereover; each of said rotary cutter spindles of each of said spindle units being also mounted for feeding movements axially toward and from said indexing table independently of and during universal lateral movements thereof; a powered master unit on each of said powered spindle units in operative connection with said rotary spindle of said unit for universally laterally moving said rotary spindle over said indexing table; each of said powered master units including an electric driving motor therefor and a current supply circuit connected with said driving motor; each of said powered spindle units having a powered spindle feed mechanism for feeding its said rotary cutter spindle axially; each of said powered spindle feed mechanisms including an electric driving motor therefor and a current supply circuit connected with said driving motor; a control circuit network connected with said current supply circuits to said driving motor of said powered indexing mechanism, said driving motors of said powered master units, and said driving motors of said spindle feed mechanisms; said control circuit network being selectively operable to effect opening or closing of said supply circuits to said driving motors of said indexing mechanism, said powered master units and said powered feed mechanisms; a first set of normally closed limit switches in said control circuit network effecting, when closed, the operation of said network to close said supply circuits to said master unit driving motors and to said spindle feed mechanism driving motors; said limit switches of said first set of limit switches being operable to and held in open positions by said powered master units when the latter are in positions at the completion of their operating cycles and restoring to normally closed positions thereof when said powered master units move from said positions thereof at the completion of their operating cycles; a second set of normally closed limit switches in said control circuit network operable by said spindle feed mechanisms to open positions when said spindle feed mechanisms are in positions at the completion of their feeding cycles for effecting operation of said control circuit network to open said supply circuits to and stop operation of said driving motors of said powered

master units and said spindle feed mechanisms only when said limit switches of said first set of limit switches are held in open positions by said powered master units in the positions of the latter at the completion of their operating cycles; said second set of limit switches restoring to normally closed positions when said spindle feed mechanisms moved from their positions at the completion of the feeding cycles; said first set of limit switches being rendered ineffective to cause operation of said control circuit network to open said supply circuits to and stop operation of said driving motors of said master units and said feed mechanisms when said limit switches of said second set of limit switches are closed; a third set of normally open limit switches connected in said control circuit network for closing to effect operation of said network to close the current supply circuit to said driving motor of said powered indexing mechanism for operation of the latter to index said indexing table through one step; and means interlocking said limit switches of said third set of limit switches with said limit switches of said first set of limit switches, respectively, for opening said limit switches of said third set when said limit switches of said second set are closed and for closing said limit switches of said third set when said limit switches of said first set are open.

9. In the combination of claim 8 a normally open start limit switch and a time relay controlled thereby in said control circuit network; said time relay being normally open and closed by closing of said start switch; said normally open start limit switch being operable to closed position by said powered indexing mechanism upon the completion of an indexing operation of the latter to effect closing of said time relay and operation of said control circuit network to close said current supply circuits to said driving motors of said powered master units and said powered feed mechanisms to start the cycles of operation of said units with said first set of limit switches held in open positions by said powered master units; and said time relay restoring to normally open position following closing by said start limit switch after a predetermined period of time.

10. In combination, a rotatable indexing table; means for indexing said table step-by-step through successive positions of index; a plurality of powered-spindle units mounted spaced from and spaced apart around said indexing table and extending radially inwardly distances thereover; each of said spindle units including a rotary spindle mounted thereon in position over said indexing table with its axis generally normal to the plane of said table for universal lateral movements over the latter; each of said rotary spindles being also mounted for movements axially toward and from said indexing table during and independently of universal lateral movements of the said rotary spindle; means on each of said powered spindle units for universally laterally moving its said rotary spindle over said indexing table; a powered spindle feed mechanism for each of said rotary spindles for power feeding its said rotary spindle toward said indexing table from an inactive position to a working position at said indexing table; each said powered spindle feed mechanism including an electric driving motor therefor and a current supply circuit connected with said driving motor; a retraction means for each of said rotary spindles for retracting said spindle to inactive position for power feed thereof to working position by its said powered feed mechanism; each of said powered means for universally laterally moving said rotary spindles of said spindle units over said indexing table including an electric driving motor and a current supply circuit connected therewith; a spindle feed mechanism control means connected with said current supply circuits to said feed mechanism motors operable by said feed mechanisms to effect opening of said current supply circuits to stop feeding of said rotary spindles upon completion of the feeding cycles thereof; said spindle feed-

ing mechanisms including release means for releasing the said rotary spindles for retraction to non-working positions by said spindle retraction means upon the completion of the power feeding cycles of said spindle feed mechanisms; and means operable by said power means for universally laterally moving said rotary spindles connected with said current supply circuits for effecting opening of said latter circuits to stop operation of said powered means for universally laterally moving said rotary spindles upon completion of operating cycles thereof.

11. In combination, a supporting frame structure; an indexing table rotatably mounted on said supporting frame structure; said indexing table providing a marginal portion therearound having a plurality of work stations spaced apart thereon and therearound; powered means for rotating said indexing table step-by-step to bring said work stations to successive positions of index; a plurality of powered spindle units mounted in positions on said supporting frame structure spaced from and spaced apart around said indexing table disposed radially relative thereto and extending inwardly over said work stations on said marginal portion of said indexing table; each of said powered spindle units having a rotary spindle mounted on the inner end thereof in position over said work stations of said indexing table with its axis substantially normal to the plane of rotation of said indexing table for universal lateral movements thereover; each of said spindle units having a profile surface thereon, a tracer member mounted for movements along said profile surface in tracing relation therewith through an operating cycle, and powered means for moving said tracer through an operating cycle; each of said spindle units having a movement transmitting mechanism connecting its said tracer member with its said rotary spindle; each of said rotary spindles of each said spindle units being also mounted for movements axially toward and from said indexing table between a working position at a work station of said table and a non-working position retracted therefrom; and powered means for feeding each of said cutter spindles from retracted position to working position at a work station indexed to position therebelow by said indexing table.

12. In combination, a supporting frame structure; an indexing table rotatably mounted on said supporting frame structure; said indexing table providing a marginal portion therearound having a plurality of working stations spaced apart thereon and therearound; powered indexing means for rotating said worktable step-by-step to bring said work stations to successive positions of index; a plurality of powered spindle units mounted in position on said supporting frame structure spaced from and spaced apart around said indexing table and extending inwardly over said work stations on said marginal portion of said index table; each of said powered spindle units having a rotary spindle mounted on the inner end thereof in position over said work stations of said indexing table with its axis substantially normal to the plane of rotation of said indexing table for universal lateral movements thereover; powered means on each of said spindle units for universally laterally moving said rotary spindle on said unit; each of said rotary spindles of each of said spindle units being also mounted for movements axially toward and from said indexing table between a working position at a work station of said indexing table a non-working position retracted therefrom; powered means for feeding each of said rotary spindles of said spindle units from a retracted position to working position at a work station indexed to position by said indexing table; a first control means operated by said spindle units for stopping both lateral movements and feeding movements of said rotary spindles of said spindle units when said spindles have completed predetermined cycles of operation; a second control means operated by said first control means upon operation of the latter to stop lateral and feeding movements of said rotary spindles for rendering

said powered indexing means operative for rotating said indexing table through an indexing step and for rendering said powered indexing means inactive during lateral and feeding operations of said rotary spindles of said spindle units.

13. In the combination of claim 12, a third control means operated by said indexing table upon the completion of an indexing step thereof for operating said first control means to initiate and effect operation of said powered means for laterally moving and of said powered feed mechanisms for feeding said rotary spindles of said powered spindle units. 10
